ABSTRACT OF THE DISCLOSURE

A solid-state traffic actuated multi-phase intersection right-of-way control system capable of providing right-of-way to up to two of a plurality of non-conflicting traffic phases selected from a larger plurality of traffic phases at an intersection. Gating and control circuitry selects the traffic phases to which right-of-way is to be assigned, insuring that right-of-way is not simultaneously assigned to conflicting traffic phases. Timing and counter circuitry steps each right-of-way period through its appropriate intervals. The right-of-way assignment can be changed from first and second non-conflicting traffic phases to third and fourth non-conflicting traffic phases, and one of the third and fourth phases may be the same as one of the first and second phases.

BACKGROUND OF THE INVENTION

This invention relates to a traffic actuated multiphase traffic intersection right-of-way control system. More particularly this invention relates to such a traffic intersection right-of-way control system including all solid state circuitry in modular components and having the ability to assign right-of-way to one or more non-conflicting phases of a plurality of traffic phases at an intersection in accordance with the demand on any one phase relative to the overall demand on all traffic phases.

While many traffic intersections are primarily utilized by traffic flowing straight through on one thoroughfare or straight through on the other intersecting thoroughfare, numerous intersections handle large quantities of traffic desiring to turn left from one thoroughfare, across the traffic lanes assigned for traffic flow in the opposite direction on that first thoroughfare, and into the second thoroughfare. So long as this left-turn traffic is of a small volume it presents no great problem. However, when the volume of left-turn traffic increases appreciably, it becomes desirable to assign portions of the right-of-way period exclusively for the left-turn traffic. For example, at an intersection of a north-south street and an east-west street, some traffic traveling in a northerly direction may desire to turn left onto the east-west street to then travel in a westerly direction. To best accommodate large volumes of this left-turn traffic it is necessary to end the right-of-way period of the south-bound traffic so that the left-turn traffic may pass in front of it.

If there is south-bound traffic desiring to turn left into the east-bound lane, then, these two left-turn flows can take place simultaneously. This necessitates stopping the straight through north-bound traffic. If, however, there is no left-turn traffic in the south-bound lanes, then the north-bound left-turn traffic can proceed simultaneously with the north-bound straight through traffic. Thus, the north-bound left-turn traffic can proceed simultaneously either with the south-bound left-turn traffic or with the north-bound straight through traffic. Similarly, the south-bound left-turn traffic can proceed simultaneously either with the north-bound left-turn traffic or the south-bound straight through traffic, and the north-bound straight through traffic and south-bound straight through traffic

2

each can proceed simultaneously with their corresponding left-turn traffic or simultaneously with each other. Left-turn east-bound and west-bound traffic similarly each have two traffic flows with which they can proceed. Thus, it is seen that at such an intersection any one traffic flow can safely take place at the same time as either one of two selected other traffic flows. Optimum assignment of right-of-way between the conflicting phases of the traffic flow requires that any one phase be permitted to operate simultaneously with either one of its non-conflicting phases which has a demand for right-of-way.

Traffic control systems are available for providing right-of-way to each of two mutually conflicting traffic phases at an intersection. Use of such a control system at 5 an intersection having large amounts of conflicting straight through and left-turn traffic results in the left-turn traffic encountering a great deal of difficulty. Not only does this result in only a few left-turn vehicles passing during each cycle of the control system, but also it presents a hazard 10 because more vehicles attempt to turn left than can, with a resulting conflict between these left-turn vehicles and vehicles attempting to travel straight through on the subsequent phase. Left-turn traffic at a two-street intersection can be accommodated by use of a three-phase or a four-phase traffic controller. Then, one phase is assigned exclusively for left-turn traffic in a three-phase controller or two phases of a four-phase controller are assigned for the two left-turn movements, i.e. one left-turn movement 15 by the north-south traffic and another left-turn movement by the east and west bound traffic. The controller then cycles through its phases to periodically allocate right-of-way to this left-turn traffic. While this smoothes the traffic flow somewhat, it does not make optimum utilization of traffic control equipment and it needlessly holds up one 20 direction of straight through traffic when there is no traffic turning left across its pathway until the left-turn traffic originating from the same direction as that straight through traffic has terminated. Thus, optimum traffic handling is not obtained.

25 40 Left-turn traffic can also be accommodated by adding to a control system one or more small control units, frequently referred to as minor movement controllers, which interrupt the normal traffic signal cycle sequence to provide left-turn indications prior to the straight through indications. By use of one such minor movement controller for each direction of left-turn traffic, improved traffic flow can be obtained. However, the left-turn indication can only be provided at one selected point in the traffic controller cycle. Thus, if at the time that point is 30 reached there is no demand for the left-turn indication, then the left-turn is omitted, and the straight through indications are provided. If, shortly after the initiation of a straight through indication a demand for a left turn originates on that phase, that demand must remain unsatisfied until the selected point in the cycle is again reached. If there is no demand on the intersecting roadway, either right-of-way must still be transferred to that roadway in order to cycle through to the point at which the minor movement controller can allow left-turn traffic 35 45 50 55 60 65 70 to have the right-of-way, or further control equipment must be added to enable the system to skip the phase having no demand. Thus, obtaining optimum traffic control with such a system requires numerous complex pieces of control equipment, thereby increasing the likelihood of an equipment malfunction.

Traffic control systems have been developed which are of unitary design and which are able to improve traffic flow by omitting one or more phases of a traffic controller cycle in order to provide a left-turn indication when demanded on a street which has right-of-way, in the absence of a call for the traffic right-of-way from a conflict-

ing phase. These traffic control systems heretofore have been large units utilizing vacuum tubes, relays, cams, and other electro-mechanical devices. Not only do such systems consume large amounts of power, they also are subject to frequent breakdown due to the nature of the electro-mechanical devices.

In addition, prior art traffic control systems of this type have been incapable of adequately handling traffic approaching the intersection in waves or platoons. Consider, for example, an intersection of two streets, at least one of which has a high volume of left-turn traffic for which a separate traffic phase is assigned. Each right-of-way period comprises several intervals. There will be an initial green interval, which may coincide with pedestrian walk and pedestrian clearance intervals if these are provided. Then there is a vehicle or passage interval during which right-of-way is continued on that traffic phase so long as the traffic volume on that phase justifies. This is followed by a brief interval, frequently known as a preparatory interval, during which the control system determines the phase to which right-of-way is to be transferred next. Then comes the yellow or clearance interval and perhaps an all-red interval for the traffic phase, following which right-of-way is transferred to another phase. If right-of-way at an intersection is assigned to a straight through traffic phase, for example east-bound straight through, and to the non-conflicting left-turn traffic phase (i.e. east-bound left-turn becoming north-bound) when a call for right-of-way is received from the opposite non-conflicting straight through phase, (i.e., west-bound straight-through) followed by a call for right-of-way from a conflicting traffic phase, for example, north-bound, prior art traffic control systems of this type have permitted the east-bound straight through phase circuitry to advance to its preparatory interval regardless of the status of the west-bound straight through right-of-way period, provided the straight-through traffic on the east-bound phase at some time reaches a low volume. But right-of-way is not transferred to the conflicting north-bound phase until the west-bound straight-through phase has passed through its vehicle interval to its preparatory interval. During the time the west-bound phase is in its initial interval, the east-bound traffic volume may increase considerably due to the arrival of another wave or platoon of traffic at the intersection. However, in prior art traffic control systems of this type, the east-bound phase circuitry is held in its preparatory condition. Thus, if the west-bound traffic volume drops, right-of-way transfers to the conflicting north-bound phase, cutting off the east-bound platoon which is at the intersection. As a consequence, optimum traffic flow is not achieved.

SUMMARY OF THE INVENTION

The present invention is a traffic-actuated multi-phase traffic intersection right-of-way control system in which during the time right-of-way is assigned to one traffic phase, right-of-way can also be assigned to any one of a plurality of non-conflicting traffic phases selected from a larger plurality of traffic phases at the intersection. The control system can change the right-of-way assignment from one of the non-conflicting traffic phases to another non-conflicting phase, while retaining right-of-way on the second non-conflicting traffic phase, as traffic demands require and in the absence of a call for right-of-way on the conflicting traffic phases. In the event that right-of-way is given to a straight through traffic phase simultaneously with its non-conflicting left-turn traffic phase, and a call comes in for the non-conflicting straight through right-of-way followed by a call for right-of-way on a conflicting traffic phase, the first straight through traffic right-of-way is maintained in its vehicle interval at least until the right-of-way period has been assigned to the other straight through traffic and has reached its vehicle interval. Thus, a platoon of traffic arriving on the first straight through phase while the second straight through phase is in its

initial interval is optimally handled. The traffic control system is made up entirely of solid state circuitry, with no vacuum tubes or moving parts, and it is adapted for simplified modulator construction, thus permitting easy expansion of the system to meet the growing requirements of an intersection.

It is accordingly an object of the present invention to provide an improved traffic actuated multi-phase traffic intersection right-of-way control system.

It is another object of the present invention to provide an improved traffic-actuated multi-phase intersection controller having a simplified solid state design resulting in improved performance and reliability.

It is a further object of the present invention to provide a traffic controller which permits optimum assignment of right-of-way at intersections having complex traffic requirements.

It is yet another object of the present invention to provide a traffic intersection right-of-way controller which, during the time that right-of-way is available to any one traffic phase, can assign right-of-way simultaneously to any one of a plurality of non-conflicting traffic phases and which in response to a demand therefor can change that assignment to any other non-conflicting traffic phase in the absence of a call for right-of-way from a conflicting traffic phase.

It is a still further object of the present invention to provide a traffic intersection right-of-way control system capable of simultaneously allocating right-of-way periods, each having a plurality of intervals, to first and second non-conflicting traffic phases at an intersection and, when a call for right-of-way is received from a third traffic phase conflicting with the second phase but not with the first, capable of holding the right-of-way period of the first phase in an intermediate interval from which it can not be removed in the presence of continuing traffic demand even in the presence of a call for right-of-way from a fourth phase, conflicting with the first three phases, where the fourth phase call arrives after the third phase call, the first phase right-of-way being held in that intermediate interval at least until the third phase has received right-of-way and has reached the corresponding intermediate interval.

These and other objects and advantages of the present invention will be apparent from the following detailed description and claims, particularly when taken in conjunction with the accompanying drawings.

BRIEF DESCRIPTION OF THE DRAWINGS

FIG. 1 is a plan view of a street intersection at which the right-of-way is controlled by the traffic actuated multi-phase control system of the present invention.

FIG. 2 is a block diagram of the traffic actuated multi-phase traffic control system of the present invention.

FIG. 3 is a detailed block diagram of the counter circuitry within the interval sequence units used in the present invention.

FIG. 4 is a detailed block diagram of a phase control unit for use in the present invention in connection with any of the traffic phases.

FIG. 5 is a detailed block diagram of the gating and timing circuitry within an interval sequence unit as used in the present invention.

FIG. 6 is a detailed block diagram of gap timing circuitry within the interval sequence units used in the present invention.

FIG. 7 is a detailed block diagram of a passage timing circuit within the interval sequence units used in the present invention.

FIG. 8 is a block diagram of the phase sequence unit of the present invention showing in detailed block form the portion of the phase sequence unit which works in common with all traffic phases at the intersection.

FIG. 9 is a block diagram depicting one set of phase

selection circuitry within the phase sequence unit used in the present invention.

FIG. 10 is a detailed block diagram of the transfer gating circuitry within the phase sequence unit used in the present invention.

FIG. 11 is a detailed block diagram of a set of hold gating circuitry utilized to coordinate operation of the system and found within the phase sequence unit used in the present invention.

DESCRIPTION OF A PREFERRED EMBODIMENT

FIG. 1 depicts a street intersection which may be controlled by means of a multi-phase traffic actuated intersection control system incorporating the present invention. The intersection depicted in FIG. 1 includes two streets, each having two lanes of travel in each of two directions, the two lanes of travel being divided by a median or divider strip. There is provided in each direction of travel for a brief distance approaching the intersection an additional lane for the convenience of vehicles desiring to make a left turn into the cross street. The east-west street is designated street I, while the north-south street is designated street II. There are thus eight phases of traffic approaching the intersection: phase A1, the straight through west-bound traffic; phase A2, the straight through east-bound traffic; phase A3, the straight through south-bound traffic; and phase A4, the straight through north-bound traffic; phase B1, the east-bound left-turn traffic becoming north-bound; phase B2, the west-bound left-turn traffic becoming south-bound; phase B3, the north-bound left-turn traffic becoming west-bound; and phase B4, the south-bound left-turn traffic becoming east-bound. These designations are of course only for convenience and are in no way limiting. By means of these designations it is seen that each straight through traffic phase is designated as an A phase while each left-turn traffic phase is designated as a B phase. In addition, it can be seen from FIG. 1 that each odd traffic phase conflicts with all other odd traffic phases and that each even traffic phase conflicts with all other even traffic phases. In addition, there are conflicts between certain odd-even pairs of traffic phases such as phases B1 and B4, phases B1 and A4, and phases A2 and A3, for example. The pairs of non-conflicting traffic phases which can operate simultaneously at the illustrative intersection depicted in FIG. 1 are thus the following: phases A1 and A2, phases A1 and B2, phases A3 and A4, phases A3 and B4, phases B1 and A2, phases B1 and B2, phases B3 and A4, and phases B3 and B4. Each of these pairs is seen to include one odd phase and one even phase due to the designations used in this illustrative example.

Vehicles on each traffic phase approaching the intersection are monitored by a vehicle detector, depicted in FIG. 1 by the vehicle detector blocks D shown in the roadway approaching the intersection for each traffic phase. Thus, for example, vehicles on phase A1 are monitored by detector DA1, vehicles on phase B3 are monitored by vehicle detector DB3, etc. Each of these vehicle detectors may be any one of a number of types. For example, each may be an overhead detector of a radar or sonic type. Alternatively each may be imbedded in the roadway, in which case they may be inductive loop, magnetic, or treadle detectors, for example. It is required only that each detector generate an electrical signal upon the passage of a vehicle in its detection zone, although a detector providing an electrical signal in response to the presence of a vehicle may be used, if desired.

Manually actuated push-buttons are provided at the corners of the intersection, to be actuated by pedestrians desiring to cross the intersection. These pedestrian push-buttons are shown in each corner of the intersection by the outlines P, and they are designated in accordance with the vehicle phase with which they cooperate. Thus, a push-button PA1 is utilized by pedestrians wishing to cross the

intersection in a direction parallel with vehicle phase A1, etc. Pedestrians desiring to cross the intersection push the appropriate pedestrian button to actuate circuitry in the invention which results in signalling of a pedestrian right-of-way interval.

5 Traffic control signals to control right-of-way phases for each traffic phase and for each pedestrian phase are provided at the intersection. For clarity these traffic control signals are collectively depicted in FIG. 1 by the circle S at the center of the intersection; however, they might conveniently be located directly in front of the traffic lanes corresponding to each phase and directly facing pedestrians desiring to cross the intersection.

10 Each of the vehicle detectors D and pedestrian push-buttons P and the traffic control signal S is connected by means of cabling (not shown) to a terminal box TB illustratively shown in one corner of the intersection. Such a terminal box housing the necessary circuitry for the present invention might be placed at any convenient location at or near the intersection or might be placed at a remote location.

15 FIG. 2 depicts the multi-phase traffic actuated intersection control system of the present invention in block diagram form. A phase control unit is associated with each traffic phase at the intersection. Thus, phase control unit 10 is associated with the traffic phase A1, phase control unit 12 is associated with traffic phase A3, phase control unit 14 is associated with traffic phase B1, phase control unit 16 is associated with traffic phase B3, phase control unit 18 is associated with traffic phase A2, phase control unit 20 is associated with traffic phase A4, phase control unit 22 is associated with traffic phase B2, and phase control unit 24 is associated with traffic phase B4.

20 Each phase control unit receives indications from its associated vehicle detector and pedestrian push-buttons and transmits signals to the associated vehicle and pedestrian signal lights. Phase control unit 10 associated with traffic phase A1 is typical of the phase control units which are associated with the four phase A traffic phases.

25 Phase control unit 10 receives vehicle detection signals from the vehicle detector DA1 and receives pedestrian call signals from the pedestrian push-buttons PA1. Phase control unit 10 provides appropriate outputs for control of the vehicle and pedestrian signal lights of phase A1 for control of right-of-way and clearance. Each of the other phase A control units 12 for A3, 18 for A2, and 40 for A4 is similar to phase control unit 10, but has inputs from the vehicle detector and pedestrian push-button of the associated phase and has outputs for the traffic control signals for such phase.

30 Phase control unit 14, associated with traffic phase B1, is typical of the phase control units which are associated with the four B traffic phases. Control unit 14 receives vehicle detection indications from vehicle detector DB1 and provides control outputs to vehicle traffic signals associated with phase B1. Phase control units 16, 22, and 24 associated respectively with traffic phases B3, B2, and B4 similarly receive vehicle indications from the vehicle detectors DB3, DB2, and DB4 associated with their respective traffic phases and provide vehicle control signals to the associated traffic signals. Since the B traffic phases are left-turn phases at the intersection of FIG. 1, no pedestrian actuations or pedestrian control signals are associated with the phase control units at phase B.

35 Each of the phase control units 10, 12, 14, 16, associated with the odd traffic phases, is connected to interval sequence unit 26 which determines the sequence of intervals for the control periods of the odd traffic phases. These odd phase control units both receive signals from interval sequence unit 26 and apply signals to interval sequence unit 26. Similarly, each of the phase control units 18, 20, 22, 24, is connected to interval sequence unit 28 which determines the sequence of intervals for the control periods of the even traffic phases. Each even phase 45 control unit 18, 20, 22, 24 both receives signals from

75

interval sequence unit 28 and applies signals to interval sequence unit 28.

Each of the phase control units 10-24 and each of the interval sequence units 26 and 28 is connected to phase sequence unit 30 to both receive signals therefrom and apply signals thereto. Phase sequence unit 30 determines which phase control units shall provide right-of-way indications at any one time and which phase control units shall be next to supply right-of-way indications, insuring that no conflicting right-of-way indications are provided. At any one time one of the odd phase control units 10, 12, 14, 16 may be selected by phase sequence unit 30 to provide control indications to its associated traffic phase and a non-conflicting one of the phase control units 18, 20, 21, 24 may be simultaneously selected to provide control indications to its associated traffic phase.

The phase control units selected by phase sequence unit 30 from the phase control units 10-24 provide appropriate control indications for their associated traffic phases and develop voltage analogs of the durations of each interval of the control sequence. Interval sequence unit 26 monitors these analog timing signals for the selected odd traffic phase, and in response to these monitored signals, the interval sequence unit 26 provides indications for a sequence of steps and appropriate intervals for the control period of that selected odd phase control unit. Similarly, interval sequence unit 28 monitors the analog timing signals for the selected even traffic phase control unit and provides indications for a sequence of steps and appropriate intervals for the control period for that selected even phase.

INTERVAL COUNTER—FIGURE 3

FIG. 3 depicts a nine position counter, one of which is used in each interval sequence unit. The counter comprises two three-position units 52 and 54. Each of these units comprises a trinary counter, and the two units are connected to obtain nine discrete count positions. A trinary counter suitable for this use is disclosed in U.S. Patent No. 3,267,424 granted to Peter C. Brockett and Charles L. DuVivier on Aug. 16, 1966, particularly in conjunction with components 356 and 356' in FIGURE 5 of that of that patent. The outputs of the three stages of each of the counter units 52 and 54 are coupled to AND gates 56-72 in such a manner that the outputs of the gates 56-72 correspond respectively with the positions 1-9 of the counter output. Pulses applied to the stepping input of counter unit 52 via line 74 sequentially step the counter through its nine positions. Thus, if the counter is in its position 1 so that signals are applied to the two inputs of AND gate 56, then gate 56 provides an output signal. Application of a pulse on line 74 steps the counter to its position 2, resulting in termination of the signal applied from counter unit 52 to AND gate 56 and application of signals to the two inputs of AND gate 58. Thus, the position 1 output from gate 56 ends and a position 2 output signal is provided from gate 58. The next pulse on line 74 steps the counter to its position 3, thereby terminating the output from gate 58 and initiating an input from AND gate 60. Under some conditions the advance pulse is blocked from line 74 and instead sets the counter to another position which skips one or more intermediate positions, as explained more fully hereinafter. When the counter is in its position 9, a pulse on line 74 returns it to position 1, returning the position 1 output signal from gate 56.

The counter position outputs 1-9 obtained from gates 56-72 respectively as the nine position counter moves through its positions correspond to intervals in the control period. Thus the first counter position, in which an output is obtained from gate 56, corresponds to the first interval of the control period known as the "green skip" interval. This is a short duration interval providing a green or go indication to vehicular traffic while maintaining a "don't walk" or "wait" indication for pedes-

trians. Should it be desired to provide sub-cycles by use of auxiliary control equipment, these sub-cycles can be operated while the counter is in its position 1. If necessary, the green indication can be inhibited during such a sub-cycle.

The second position of the counter, during which an output is obtained from gate 58, corresponds to the pedestrian interval of the control period. During this interval a green indication is provided for vehicular traffic and a "walk" indication is provided for pedestrian traffic. During the third counter position an output is provided from gate 60 to cause a green indication for vehicular traffic and a clearance interval for pedestrians, during which the pedestrian indicators may provide a flashing "don't walk" or a flashing "wait" indication, for example.

In position 4 of the counter an output is generated by gate 62. During this condition a green indication is provided for vehicular traffic and a "wait" indication for pedestrians. This counter position corresponds to the initial interval of the control period during which the intersection may be entered by vehicles which had approached the intersection during the red indication and which were between the vehicle detector and the intersection waiting for right-of-way. Position 5 of the counter corresponds to the vehicle interval of the control period. In this position an output is obtained from gate 64, and a green indication is provided to vehicular traffic while a "wait" indication is provided to pedestrians. The sixth position of the counter is a preparatory interval during which phase sequence unit 30 determines which phases of the intersection are to have right-of-way next, as will be more fully described hereinafter. During this preparatory interval a signal is obtained from gate 66 to cause a green indication for vehicular traffic and a "wait" indication for pedestrians.

In position 7 of the counter an indication is provided from gate 68 to cause a yellow or clearance indication for vehicular traffic and "wait" indication for pedestrians. This is the vehicle clearance interval. The eighth counter position corresponds to the all red interval of the control period during which a red indication is provided to all vehicular traffic and a wait indication to all pedestrians. In this position an output is provided from gate 70. The ninth counter position is a transfer position during which a signal is provided from gate 72. In this position all the vehicular indicators provide a red indication and the pedestrian signals provide "wait" indications. During this transfer interval, transfer is made from the phase timing unit which has just completed its control period to the phase timing unit to which the next control period is assigned.

The output of the last stage of counter unit 54 is connected to the input of inverter 76 so that during counter positions 7, 8, and 9 a signal is applied to the input of inverter 76. Thus, when the counter is in any one of its positions 1-6, no input is applied to inverter 76, and so the inverter supplies an output signal. During these counter positions 1-6 the vehicular traffic is provided a green indication. Thus, any time this green indication is to be provided to the vehicular traffic, inverter 76 supplies a signal, referred to as the Σ Green signal.

When the traffic control system is first placed into operation, a "start" signal is applied via line 77 to counter units 52 and 54 to set the counter to its 7 position. This causes a signal from gate 68 to energize the yellow indication for vehicular traffic. Subsequent advance pulses applied on line 74 step the counter through its positions 8 and 9 in which the control period is transferred to another phase under the control of phase sequence unit 30. The counter then returns to position 1, the green skip position. If there has been a pedestrian call on the phase to which right-of-way has now been transferred, a signal passes through OR gate 78 to block INHIBITED-AND gate 79. The next advance pulse on line 89 passes through gate 80 to step the counter to its position 2 to provide a

green indication for vehicles and a walk indication for pedestrians. At the conclusion of the pedestrian interval, an advance pulse on lines 89 and 74 steps the counter to position 3 to provide the pedestrian clearance interval. In this position a signal from gate 60 is applied to one input of AND gate 81 and via OR gate 90 to the inhibit input of INHIBITED-AND gate 80. As a consequence the next advance pulse on line 89 is blocked from line 74, and instead it passes through gate 81 and through OR gates 82 and 84 to set the counter to position 5. Thus, when a pedestrian call has resulted in the counter cycling through the pedestrian and pedestrian clearance intervals of counter positions 2 and 3, the initial interval of position 4 of the counter period is omitted, and the pedestrian and pedestrian clearance intervals replace it. The controller moves immediately to the vehicle interval of counter position 5 after the pedestrian clearance interval has terminated.

Position 5 is a rest position for the counter, and so it remains in this position until a command to step to another position is received. During counter position 5, the signal from AND gate 64 passes to one signal input of INHIBITED-AND gate 86. If there are no calls for right-of-way from a conflicting traffic phase assigned to the same interval sequence unit, the Σ no call signal is also applied to a signal input of gate 86. If no call for right-of-way is present on a conflicting phase assigned to the other phase sequence unit, the signal "call away" is not present at the inhibit input of gate 86. Should a pedestrian call then be received on the phase which has right-of-way, a signal passes through OR gate 78 to the third signal input of gate 86. Gate 86 then applies a signal through OR gate 90 to block gate 80. This same signal from gate 86 is applied to the first input of AND gate 92. Via line 88 this condition also transmits the signal "pedestrian return" to the gating and timing circuitry of FIG. 5 to cause an advance pulse on line 89, as described more fully hereinafter. This advance pulse is blocked at gate 80 and passes through gate 92 to return the counter to its position 2, thus providing a walk indication in response to that pedestrian call. Hence, the control system is capable of returning from its rest position in the vehicle interval to provide pedestrian right-of-way in the event of a pedestrian call on the phase which has right-of-way when no conflicting calls have been received.

If there has been no pedestrian call when the counter is in the green skip interval at position 1, then during the time that the counter is in position 1, the position 1 signal is applied from the output of INHIBITED-AND gate 79 through OR gate 90 to block gate 80. This signal from gate 79 is also applied to the first input of AND gate 96. The next advance pulse therefore, passes through gate 96 and through OR gates 84 and 98 to set the counter to position 4, providing a green vehicular indication and a wait pedestrian indication. This is the initial interval of the right-of-way period, and so in the absence of a pedestrian call, the pedestrian walk indication is omitted. Instead, the control system steps from counter position 1 to the vehicle initial interval in counter position 4, at the conclusion of which an advance pulse steps the counter position 5, the vehicle interval of the right-of-way period, where it rests. Hereinafter where it is stated that the counter "steps" to a position, it is meant that the counter moves to that position in response to an advance pulse.

If the control system is next to provide right-of-way for a phase conflicting with that on which right-of-way is presently provided, the counter next moves to position 6 either in response to an advance pulse or in response to the "go to prep" signal, as explained hereinafter. Position 6 is the green preparatory position during which position the phase sequence unit 30 determines the phase control unit or units to which control is next to be assigned. At the termination of the green preparatory position, the counter steps to position 7 to provide the vehicle clearance interval on the phase from which right-of-way is being

transferred. At the conclusion of the clearance interval, the counter provides a brief all-red interval in its position 8. In position 9 the actual phase transfer takes place, following which the counter steps to position 1 to provide control to the newly assigned phase.

In counter position 3, the pedestrian clearance interval, power is applied to free-running multivibrator 100 which then provides a flashing power for causing the pedestrian clearance indicator to flash in the event no flashing power is available within the indicator itself.

PHASE CONTROL UNITS—FIG. 4; GATING AND TIMING CIRCUITS—FIG. 5

FIG. 4 depicts in detail block diagram form the circuitry of each phase control unit 10-24. Each phase control unit is associated with one traffic phase at the intersection and so receives input signals from a vehicle detector, such as vehicle detector DA1, associated with traffic phase A1. This vehicle detector, shown in FIG. 4 as vehicle detector 102, applies ground to the input of inverting amplifier 104 each time a vehicle passes through its detection zone. The resulting positive pulse from amplifier 104 passes through OR gate 106 to trigger locking delay multivibrator 108. Locking delay multivibrator 108 is a monostable multivibrator including a gate to provide memory when a locking input is applied. Thus, with no locking input, a trigger input causes the multivibrator to assume its unstable state for a period of time determined by the time-constant of the multivibrator circuitry, just as in a one-shot multivibrator. With a locking input L, the multivibrator remains in its stable state until a trigger input is applied to it, at which time it assumes its unstable state and remains there until the locking input terminates. Following termination of the locking input, the multivibrator remains in its unstable state for a period of time determined by the time constant of its circuitry, after which it returns to its stable state. This locking multivibrator is hereinafter called DMV 108. A circuit suitable for this use is disclosed in FIG. 8 of U.S. patent application Ser. No. 586,881 filed Oct. 14, 1966 by Charles L. Du Vivier and Peter C. Brockett and assigned to the same assignee as the present application.

Each time a vehicle passes through the detection zone of vehicle detector 102, the one output of DMV 108 applies a pulse through OR gate 110, INHIBITED-AND gate 112, and OR gate 114 to set phase memory flip-flop (PMFF) 116 to its one condition. When the system is first placed into operation the start signal passes through OR gate 106 to have the same effect as a vehicle detection pulse. The one output from flip-flop PMFF 116 is applied through OR gate 117 to generate the output signal PMFF1, indicating that there has been a call for right-of-way on the traffic phase associated with this phase control unit. This output is applied to phase sequence unit 30. When no call has been received for this phase PMFF 116 is in its zero condition, and the signal PMFF0 is applied to AND gate 117' which provides the no call signal to the interval sequence unit of FIG. 5 where it is summed with the no call signals from other phases.

When the traffic phase associated with this phase control unit is to be the next traffic phase to have right-of-way, as determined by phase sequence unit 30, the signal PNFFS1 is applied to the set one input of phase next flip-flop (PNFF) 118. As a consequence PNFF 118 provides its one output signal PNFF1 as an input to AND gate 119. When the counter within the associated interval sequence unit reaches its position 1 at the start of its next control cycle, a signal is applied to the other input of gate 119. Consequently, a signal passes from gate 119 to the set one input of phase flip-flop (PFF) 120. This switches PFF 120 from its zero condition, in which it provides the output PFF0, to its one condition in which it provides the output PFF1. During counter positions 2 and 4 signals pass through OR gate 118' to reset PNFF 118 to its zero condition. During counter position 9 the

output of gate 72 is applied to the set zero input of PFF 120 to return the flip-flop to its zero condition. The PFF1 output of PFF 120 is applied to one input of AND gate 120'.

Counter positions 2, 3, 4, 7 and 8 pertain to intervals of the control sequence having fixed time durations for any one traffic phase. Within each phase control unit variable resistor 121 has one end connected to an input terminal to which a signal is applied from AND gate 58 when the counter of FIG. 3 is in its position 2. Similarly within each phase control unit a signal from gate 60 is applied to one end of variable resistor 122 during counter position 3; a signal from gate 62 is applied to one end of variable resistor 123 during counter position 4; a signal from gate 68 is applied to one end of variable resistor 124 during counter position 7; and a signal from gate 70 is applied to one end of variable resistor 125 during counter position 8. The second end of each of the variable resistors 121-125 comprise the inputs to OR gate 126 which has its output connected to the first plate of capacitor 127. The second plate of capacitor 127 is tied to ground.

When this phase control unit is not controlling right-of-way, the signal PFF0 from PFF 120 passes sequentially through OR gates 128 and 130 to the input of gating amplifier 132. When a signal is applied to the input of gating amplifier 132, the amplifier output is substantially ground potential, clamping capacitor 127 to that potential. With no input to gating amplifier 132, its output line is open circuited, permitting voltage to build up on capacitor 127 due to current through one of the resistors 121-125.

When this phase control unit is controlling the intersection, signal PFF0 is not present, and so capacitor 127 is not clamped to ground. Then, during counter position 2, resistor 121 and capacitor 127 form a circuit which develops a voltage analog of the time duration of the pedestrian interval of the control sequence. Similarly, in counter positions 3, 4, 7, and 8, the corresponding resistors 122-125 together with capacitor 127 develop voltage analogs of the time durations of the corresponding intervals of the control period.

The output of this interval timing circuit is obtained from the first plate of capacitor 127 through diode 134 to output terminal 136 which ties it to terminal 138 within the gating and timing circuitry of the associated interval sequence unit, as shown in FIG. 5. From terminal 138 the signal passes through OR gate 140 and INHIBITED-AND gate 141 to Schmitt trigger 142. Since the firing level of Schmitt trigger 142 is fixed, the time durations of the various intervals of the control period are determined by the length of time required for the voltage analog on capacitor 127 to reach this firing level. That length of time is determined by the adjustment of the corresponding variable resistor 121-125. OR gate 140 also receives an input during counter position 1 to fire Schmitt trigger 142 during the green skip interval. The output of Schmitt trigger 142 is tied to the input of direct coupled monostable multivibrator 144 (hereinafter referred as direct coupled delay multivibrator or DC DMV). Since the input to the DC DMV is direct coupled, its output signal is present so long as the input signal is applied. Upon termination of the input signal, the DC DMV output continues for a fixed length of time, similar to the operation of AC coupled one-shot multivibrator upon application of a triggering pulse. The output from DC DMV 144 passes through OR gate 148, INHIBITED-AND gate 150, and OR gate 152 to trigger monostable multivibrator or one-shot 154. The output of one-shot 154 is the advance pulse on line 89 which causes counter units 52 and 54 to step through their counting cycle. Thus, it is seen that during those intervals of the control sequence which have fixed time durations, the timing circuit comprising one of the resistors 121-125, capacitor 127 and Schmitt trigger 142, operates with DC DMV 144 and

one-shot 154, to provide the proper time duration for that interval before generating the advance pulse.

OR gate 152 also receives an input on line 88 from gate 86 within the counter circuitry of FIG. 3 when a pedestrian call has been received on the phase which is resting in its vehicle interval in the absence of a call from a conflicting phase. This input causes the advance pulse which returns the counter to its position 2 to provide a walk signal.

Within the timing circuitry of FIG. 5, the advance pulse obtained from one-shot 154 is applied through OR gate 156, the output of which is the interval timer reset signal that is transmitted to each phase control unit. Within the phase control unit of FIG. 4 this interval timer reset signal passes through OR gate 130 to the input of gating amplifier 132, discharging capacitor 127 to ground.

So long as there is no call from a phase conflicting with that phase which has right-of-way, then the signal Σ no call passes through INHIBITED-AND gate 162 in the interval sequence unit gating and timing circuitry of FIG. 5. This signal then passes through OR gate 164, the output of which is the maximum timer reset signal which is applied to each phase timing unit. The signals for counter positions 2, 3, and 4 pass through OR gate 166 in FIG. 5 to the inhibit input of INHIBITED-AND gate 168, which has the advance pulse applied to its signal input. Thus, during the counter positions 2, 3, and 4 the advance pulse is blocked from passage through gate 168. The output of gate 168 is tied to the input of OR gate 164 from which the maximum timer reset signal is obtained.

As shown in FIG. 4, each phase control unit includes a maximum timer, comprising capacitor 170 and variable resistor 172 tied together between a source of positive voltage and ground. When another phase control unit is controlling the intersection, the signal PFF0 passes sequentially through OR gates 128 and 174 to gating amplifier 176 which clamps capacitor 170 to ground, operating in the same manner as amplifier 132. Similarly, the maximum timer reset signal is applied through gate 174 to gating amplifier 176 to discharge capacitor 170. When the intersection comes under control of this phase control unit, signal PFF0 is no longer applied to amplifier 176.

If no call for right-of-way has been received from a conflicting traffic phase, the signal Σ no call passes through gates 162 and 164 of FIG. 5, becoming the maximum timer reset signal. This signal passes through gate 174 to gating amplifier 176, preventing voltage build-up on capacitor 170. When a call is received from a conflicting traffic phase assigned to the same interval sequence unit, the signal Σ no call ends. When a call is received from a conflicting traffic phase assigned to the other interval sequence unit, phase sequence unit 30 generates the signal "call away" which is applied through OR gate 177 to block gate 162. In either case the maximum timer reset signal ends, and voltage builds up on capacitor 170 at a rate determined by the setting of adjustable resistor 172.

This maximum time voltage on capacitor 170 of the phase control unit of FIG. 4 is applied to the input of Schmitt trigger 178 within the timing and gating circuitry of FIG. 5. When Schmitt trigger 178 fires, its output activates DC DMV 180. The output of DC DMV 180 passes through INHIBITED-AND gate 181, becoming the signal "go to preparatory." This signal is applied to line 181' of the interval sequence unit counter circuit (FIG. 3) to set the counter to its position 6, the preparatory position. The signal from gate 181 also passes through OR gate 156 and 164, generating the interval timer reset signal and the maximum timer reset signal. Thus, this maximum timer determines the maximum length of time for the part of the right-of-way period overlapping positions 1-5 of the counter for the phase holding the right-of-way

against a car waiting on another phase, before the phase which has right-of-way is stepped to its green preparatory interval, position 6 of the counter.

In counter position 5, voltage is applied through variable resistor 182 within the phase control unit of FIG. 4 to one side of capacitor 183, the other side of which is grounded. OR gate 184 receives as inputs the signals from counter positions 2, 3, and 4. The output of OR gate 184 is applied to the input of gating amplifier 185 so that during counter positions 2, 3, and 4 gating amplifier 185 clamps capacitor 183 to ground. Then, when the counter moves to position 5, gating amplifier 185 unclamps the capacitor, and voltage passes through resistor 182 to build up upon the capacitor 183. Each time a vehicle passes through the detection zone of vehicle detector 102, DMV 108 sends a pulse through OR gate 110 and INHIBITED-AND gate 186 to the input of OR gate 184. As a consequence amplifier 185 turns on to discharge capacitor 183. OR gate 110 also receives an input directly from OR gate 106 so that if a vehicle is moving very slowly through the detection zone of vehicle detector 102 capacitor 183 will be held discharged for as long as the vehicle is within the detection zone. The output of the Σ vehicle timer circuit is applied from capacitor 183 through diode 188 to Schmitt trigger 190 within the interval sequence unit gating and timing circuitry of FIG. 5. The output of Schmitt trigger 190 is connected to one input of AND gate 192 which has the signal from gate 64 applied to its other input during counter position 5. Variable resistor 182 (FIG. 4) is adjusted so that the length of time required for the voltage on capacitor 183 to build up from ground potential to the firing level of Schmitt trigger 190 is substantially the same as the average time required for a vehicle to travel from vehicle detector 102 through the intersection.

GAP MEASUREMENT TIMER—FIGURE 6

In counter position 5 a voltage is applied through resistor 194, shown in FIG. 6, to the first plate of capacitor 196 which has its second plate tied to ground. Thus, voltage builds up on capacitor 196. This voltage is applied through impedance converter 198 and resistor 200 to junction 202 which is tied to the input of Schmitt trigger 204. Impedance converter 198 acts as a buffer with high input impedance. When there is no call for right-of-way from a conflicting traffic phase assigned to the same interval sequence unit, the signal Σ no call is applied to the signal input of INHIBITED-AND gate 205. If a call for right-of-way is present from a conflicting traffic phase assigned to the other interval sequence unit, the signal "call away" blocks gate 205. Thus, in the absence of calls for conflicting right-of-way, a signal from gate 205 passes through OR gate 206 to the input of gating amplifier 208. As a consequence, amplifier 208 clamps capacitor 196 to ground. When such a conflicting call is received, this input to gate 206 terminates, and voltage commences to build up on capacitor 196. When a phase control unit is controlling the intersection, the signal PFF1 is applied to the first input of its AND gate 209, shown in FIGURE 4. Each time a vehicle passes through the detection zone of vehicle detector 102, DMV 108 sends a pulse through OR gate 110 to the other input of gate 209. Coincidence of these two inputs causes gate 209 to generate a gap reset signal which is applied to the Σ gap reset input of OR gate 206 in FIG. 6. Thus, capacitor 196 is discharged each time a vehicle passes through the detection zone of the vehicle detector on a phase which is in control of the intersection. As a consequence, the voltage on capacitor 196 is a measure of the time spacing or gap between consecutive vehicles on that traffic phase.

During counter position 5, voltage also passes through variable resistor 210, within the phase control unit of FIG. 4, to the first plate of capacitor 212 which has its second plate tied to ground. So long as there is no call for right-of-way from a conflicting traffic phase, the call away signal does not block INHIBITED-AND gate 213, and

so the Σ no call signal passes through gate 213 and through OR gate 214 to turn on gating amplifier 215 which clamps capacitor 212 to ground. Amplifier 215 is also held on by the signal PFF0 via gates 128 and 214 when the intersection is under control of another traffic phase. Once a conflicting call is received, the output of gate 213 terminates, and so voltage commences to build up on capacitor 212. This voltage passes through diode 216 within the phase control unit to the Σ gap reduction timer input of impedance converter 217 within the interval sequence unit, as shown in FIG. 6. The output of impedance converter 217 is coupled through resistor 218 to junction 202 and thus to the input of Schmitt trigger 204. The voltage at junction 202 is a function of the sum of the voltage applied to the input of impedance converter 198 and the voltage applied to the input of impedance converter 217. This voltage at junction 202 is applied to the input of Schmitt trigger 204. The voltage at the input of impedance converter 217 continually increases after a conflicting right-of-way call is present during the vehicle interval (counter position 5). As the voltage at the input of impedance converter 217 increases, the difference between this voltage and the firing level of Schmitt trigger 204 decreases. This voltage difference represents the minimum permissible gap between vehicles which will be permitted to retain right-of-way on this traffic phase. Hence the minimum permissible gap length continuously decreases once a conflicting call is received during the vehicle interval. When the voltage at the input of impedance converter 198 represents a gap exceeding the permissible minimum (i.e. the voltage at junction 202 exceeds the firing level of Schmitt trigger 204), Schmitt trigger 204 fires, and its output passes through INHIBITED-AND gate 219 to set flip-flop 220 to its one condition, thereby generating the signal "last vehicle passage" (LVP). This signal indicates that traffic on the phase having the right-of-way has reached such a light level that the gaps between consecutive vehicles exceed the minimum permissible gap, and so it is time to transfer right-of-way to the next phase which is awaiting it. OR gate 221 receives the hold signal and the counter position 1 signal at its input. The output of gate 221 is connected to the set zero input of flip-flop 220, so that when the LVP signal causes transfer of right-of-way, flip-flop 220 is reset to its zero condition during counter position 1 of the next traffic phase.

The LVP signal is applied to the inhibit input of gate 186 within the phase control unit of FIG. 4. As a consequence, subsequent vehicles passing detector 102 do not cause capacitor 183 to be discharged. Therefore, the voltage at capacitor 183 increases until it reaches the firing level of Schmitt trigger 190, shown in FIG. 5 within the interval sequence unit. The output of Schmitt trigger 190 passes sequentially through gates 192, 140, and 141 to activate Schmitt trigger 142 which turns on DC DMV 144. The DMV 144 output passes sequentially through gates 148, 150, and 152 to activate one-shot 154 which generates the advance pulse. This steps the counter of FIG. 3 to its position 6, the preparatory position.

Within the phase control unit of FIG. 4 voltage is applied through variable resistor 222 to one plate of capacitor 224 which has its other plate grounded. When this phase control unit is not controlling the intersection, the signal PFF0 passes through OR gate 226 to turn on gating amplifier 228, clamping capacitor 224 to ground. When this phase control unit is controlling the intersection signal PFF0 ends. Each time a vehicle passes detector 102, DMV 108 sends a pulse through gates 110 and 226 to turn on amplifier 228, thereby discharging capacitor 224. This discharging of capacitor 224 is not inhibited by the LVP signal. Thus, the voltage on capacitor 224 is a measure of the length of time which has elapsed since a vehicle has passed detector 102. The voltage on capacitor 224 passes through isolating diode 230 to the Σ passage timer input of Schmitt trigger 232 within

the passage timing circuitry of FIG. 7. Schmitt trigger 232 has its output connected to the input of inverting amplifier 234, the output of which is tied to one input of AND gate 236. At its other input, gate 236 receives a signal from gate 68 during counter position 7, the vehicle clearance interval. Schmitt trigger 232 turns on when the voltage on capacitor 224 indicates that sufficient time has elapsed since passage of a vehicle past detector 102 for that vehicle to have entered the intersection. Thus, whenever a vehicle is between detector 102 and the intersection, amplifier 234 applies an enabling input to gate 236. If that enabling input is present when counter position 7 is reached, a signal is generated by gate 236 to indicate that a vehicle will be waiting for right-of-way on this traffic phase after right-of-way has been removed from the phase. Within the phase control unit of FIG. 4, this vehicle waiting signal is applied to one input of AND gate 238 which receives the signal PFF1 at its other input. Gate 238 then sends a signal through OR gate 114 to set the phase memory flip-flop PMFF 116 to its one condition which indicates that right-of-way is to be returned to this traffic phase in its turn.

In the event that both phases on which right-of-way is present have reached their counter position number 5 and are to lose right-of-way, then a gap in the traffic flow on one phase in excess of the acceptable gap duration determined by the firing level of Schmitt trigger 204 (FIG. 6) initiates that traffic phase stepping from counter position 5 to counter position 6. Gating circuitry within the phase sequence unit 30, to be discussed later, causes that traffic phase to rest in this green preparatory counter position 6 until the other traffic phase has also reached its preparatory condition. The vehicle timing circuitry comprising resistor 182 and capacitor 183 insures that the last vehicle to pass the vehicle detector of the last traffic phase to come to the preparatory condition, has sufficient time to clear the intersection. However, since the other traffic phase is resting in counter position 6, its vehicle timing circuit is not operating. Consequently, if a vehicle crosses its vehicle detector just before the second traffic phase reaches its preparatory position, there might be insufficient time for that vehicle to clear the intersection. In such an event, the passage timer comprising resistor 222 and capacitor 224 results in a signal being applied from gate 236 through gate 238 and gate 114 to set the phase memory flip-flop PMFF 116 so that right-of-way will be recalled to that traffic phase. This insures that that vehicle will not be trapped on a traffic phase to which right-of-way will not be returned.

The counter position 5 signal and the counter position 6 signal pass through OR gate 240 (FIG. 4) to the first input of AND gate 242 which receives the PFF1 signal at its second input. The output of gate 242 passes through OR gate 244 to reset phase memory flip-flop PMFF 116 to its zero condition. Thus, PMFF 116 is reset during interval 5 of the control sequence and is held reset during position 6. In addition, the Σ green signal and the PFF1 signal pass through INHIBITED-AND gate 246, except with the LVP signal is applied to the inhibit input of gate 246. The output of gate 246 passes through OR gate 248 to block gate 112 so that detector pulses cannot pass to the set one input of PMFF 116. If it is desired to provide the option of automatic recall of right-of-way to this traffic phase, the PFF0 signal is applied to one contact of a vehicle recall switch 247, the other contact of which is applied through OR gate 114 to the set one input of PFF 116, as shown in FIG. 4.

Determination of which traffic phases are next to be allocated right-of-way takes place during the counter position 6 for those phases which are losing right-of-way. Thus, if a street change is to be made, requiring that both phases lose right-of-way, the determination is made during the time that both counters are in their position 6. If one transfer is to be made on the same street, then the determination is made when that one counter is in its posi-

tion 6. To insure against erroneous indications during the brief time that the determination is made, the DMV 108 within each phase control unit is locked so that actuations from vehicle detectors cannot be passed. Circuitry within the phase sequence unit 30 generates the lock detector signal which is applied to each DMV 108 and through each OR gate 248 to the inhibit input of each INHIBITED-AND gate 112. When this signal is present, DMV 108 becomes a memory device. Thus, if at the time the lock detector signal is applied, DMV 108 is in its zero condition, it remains so until a vehicle detection pulse is applied to its set input from OR gate 106. Application of that pulse causes DMV 108 to assume its one condition, and it is locked in that one condition so long as the lock detector signal is present. Thus, DMV 108 remembers that a vehicle has passed its vehicle detector while the lock detector signal is present. When the counter steps out of its position 6 the lock detector signal ends, and the output from DMV 108 passes sequentially through gates 110, 112, and 114 to set PMFF 116 to its one condition, thereby indicating that a vehicle is waiting for right-of-way on that traffic phase.

During the time that the counters in both interval sequence units are in their positions 6, signals are applied through gating circuitry within the phase sequence unit to be described later to set the phase next flip-flop PNFF 118 within the phase control units of the next traffic phases which are to have right-of-way. Phase control unit 30 then transmits the signal "preparatory leave" (PL) which is applied to OR gate 140 within the gating and timing circuitry (FIG. 5) of each interval sequence unit. This signal passes through OR gate 140, to cause the advance pulse from one-shot 154. As a consequence, the counter of FIG. 3 steps to its counter position 7, the vehicle clearance interval.

The vehicle clearance interval and the all-red interval of counter positions 7 and 8 are timed for durations determined by resistors 124 and 125, respectively, together with capacitor 127, and then the counter reaches its position 9, the transfer position. During counter position 9 phase sequence unit 30 generates a transfer signal which is applied to each interval sequence unit which is to start a new cycle. Thus, if right-of-way is on first and second non-conflicting traffic phase and is to be transferred from the second phase to a third phase which is also non-conflicting with the first, the transfer signal is applied only to the interval sequence unit associated with the second and third phases. If instead right-of-way is to be transferred to traffic phases conflicting with both the first and second phases, the transfer signal is applied to both interval sequence units.

The transfer signal, shown in FIG. 5 as signal TR, is applied to OR gate 140 to turn on Schmitt trigger 142, thereby causing one-shot 154 to generate an advance pulse. The TR signal is also applied through OR gate 166 to block gate 168 from passing the advance pulse to OR gate 164.

During the vehicle interval the counter position 5 signal from gate 64 (FIG. 3) passes through INHIBITED-AND gate 250 (FIG. 5) and OR gate 252 to the first input of AND gate 254. If there are no calls for right-of-way from traffic phases conflicting with this traffic phase, then INHIBITED-AND gate 256 passes a signal through OR gate 258 to the second input of gate 254. On coincidence of these two signals at gate 254, a signal is applied to block gate 150 from activating one-shot 154 which generates the advance pulse. Thus, when traffic on all phases is extremely light, and the vehicle timer (comprising resistor 182, capacitor 183, and Schmitt trigger 190) turns on Schmitt trigger 142, no advance pulse can be generated, unless there is actually a call for right-of-way from a conflicting traffic phase. As a consequence, the system will not slowly change back and forth, providing right-of-way on one traffic phase and then on another traffic phase during these extremely light traffic conditions.

Within the phase control unit of FIG. 4, the signal PFF0 passes through OR gate 260 to output line 262 which energizes the red indicator within traffic signal 263 for this traffic phase. The Σ green signal from inverter 76 associated with the counter circuitry is applied to one input of AND gate 264 within each phase control unit. When this phase control unit is controlling the intersection, the signal PFF1 is applied to the second input of gate 264. As a consequence, gate 264 provides a signal on its output line 266 which is applied to the traffic signal 263 at the intersection for this traffic phase to cause the green indication. AND gate 268 receives as inputs the signal PFF1 and the signal from gate 68 during the counter position 7, the vehicle clearance interval. On coincidence of these two inputs, gate 268 provides a signal on output line 270 which ties to the traffic signal 263 for this phase to cause the yellow indication. Lines 266 and 270 connect respectively to inverters 272 and 274 which have their outputs applied to the two inputs of AND gate 276. The output of AND gate 276 connects through OR gate 260 to output line 262 to cause the red indication during counter positions 8 and 9 when this phase control unit is controlling the intersection.

If this phase control unit is associated with one of the A traffic phases, which require pedestrian indications, then the pedestrian push-button shown in FIG. 4 as pedestrian push-button 278, is connected as an input to inverting amplifier 280. Inverting amplifier 282 receives the lock detector input when the control system is determining which traffic phase is next to be assigned right-of-way. Inverters 280 and 282 have their outputs applied to the two inputs of AND gate 284, thus inverter 282 applies a signal to gate 284 at all times except during the lock detector condition. Consequently, any time a pedestrian push-button is activated, except during this brief interval, inverter 280 passes a signal through gate 284 to OR gate 286 which applies the signal to the set one input of pedestrian phase memory flip-flop (PPMFF) 288. The start signal received when the control system first commences operation is also applied as an input to OR gate 286. Similarly, if it is desired to provide automatic recall to the pedestrian indications on this traffic phase, then the signal PFF0 is connected to one terminal of a pedestrian recall switch 289 which has its second terminal connected to the input of OR gate 286, as depicted in FIG. 4.

The one output of PPMFF 288 is connected as an input of OR gate 117, which also receives an input from the one output of PMFF 116. The output of OR gate 117 is the PMFF1 signal, indicating that a call has been received for right-of-way on this traffic phase. The one output of PPMFF 288 is also connected as an input to AND gate 290 which receives the signal PFF1 as its other input. When these two inputs are applied to gate 290, the gate generates the pedestrian call signal for this phase which passes through isolating diode 292 to Σ pedestrian call circuitry. INHIBITED-AND gate 294 has its signal input tied to the one output of PPMFF 288 and its inhibit input connected to the one output of PFF 120. The output of gate 294 passes through inverting amplifier 296 to one input of AND gate 117'. Thus, in the absence of a call for pedestrian indications on this phase, no signal is applied from gate 294 to inverter 296. As a consequence the inverter 296 applies an input to gate 117'. If there has been no vehicle call for this phase, then PMFF 116 applies its zero output to the other input of gate 117', and gate 117' generates the no call signal for this phase which is applied through summing diode 297 to the Σ no call circuitry. When a pedestrian actuation has been received to set PPMFF 288 to its one condition, a signal is applied by gate 294 to inverter 296. As a consequence, the output from inverter 296 to gate 117' ends, and so the Σ no call signal is terminated. When this phase control unit is controlling the intersection,

then signal PFF1 inhibits gate 294, and so inverter 296 again applies a signal to gate 117'.

AND gate 298 receives a signal from gate 58 during counter position 2 at its first input and receives the PFF1 signal from PFF 120 at its second input. Coincidence of these two inputs causes gate 298 to generate a signal on output line 300 to cause the pedestrian indicator 301 to provide the "walk" indication for the pedestrians on this traffic phase. The output of gate 298 also resets PPMFF 288 to its zero condition. AND gate 302 receives a signal from gate 60 during counter position 3 at its first input and receives the signal PFF1 from PFF 120 at its second input. Coincidence of these two signals causes gate 302 to generate a signal on its output line 304 to cause the pedestrian indicator 301 to provide the pedestrian clearance indication for this traffic phase. Output lines 300 and 304 are connected respectively through inverters 306 and 308, each of which has its output tied to an input of AND gate 310. The output of gate 310 is connected as one input to OR gate 312. INHIBITED-AND gate 314 receives the PFF1 output from PFF 120 at its signal input. The inhibit input of gate 314 is connected to the output of free-running multivibrator 100 within the counting circuitry of FIG. 3 to receive flashing power during counter position 3. The output of gate 314 is connected to the input of inverter 316 which has its output tied to the second input of OR gate 312. The output of OR gate 312 is connected to output line 318 which causes the wait indication on the pedestrian indicator 301 for this traffic phase. If the pedestrian indicator utilized with this traffic phase has its own flashing power, then gate 314, inverter 316 and OR gate 312 can be omitted, with the output line 318 taken directly from AND gate 310. Then during the pedestrian clearance interval of counter position 3, the pedestrian clearance indication on output line 304 activates this source of flashing power within the pedestrian indicator to cause a flashing "don't walk" or flashing "wait" indication for pedestrians. If the pedestrian indicator does not have its own source of flashing power, then output line 304 is not connected to the pedestrian indicator, but instead gates 312 and 314 and inverter 316 are provided as depicted in FIG. 4. During counter position 3 the flashing power interrupts the application of the signal applied to gate 314. An intermittent signal on line 318 then causes the "don't walk" or "wait" indicator to flash on the pedestrian indicator 301. During all counter positions except counter positions 2 and 3 for this traffic phase, inverters 306 and 308 both apply signals to AND gate 310 which then passes an indication through gate 312 to cause the wait indication to appear on the pedestrian indicator 301. For the phase control units associated with the B traffic phases which do not require pedestrian indications, the components 117, 117', and 278-318 of FIG. 4 are omitted.

55 PHASE SEQUENCE UNIT COMMON CIRCUITRY— FIGURE 8

FIG. 8 depicts circuitry within phase sequence unit 30 which determines when the counters within each interval sequence unit are to be stepped out of the preparatory interval of counter position 6 to the clearance interval of counter position 7. If a street change is to be made, this phase sequence unit common circuitry synchronizes operation of the two counters, thereby insuring that the right-of-way periods end at the same time on both traffic phases of the street losing right-of-way.

When the green right-of-way for a traffic phase is to end, a "preparatory leave" signal is generated within this common circuitry. A preparatory leave signal is generated for each interval sequence unit. These signals are shown as signal ISO-PL, obtained from AND gate 402 to signify that the odd interval sequence unit should leave its preparatory position, and as signal ISE-PL obtained from AND gate 404 to signify that the even interval sequence unit should leave its preparatory position.

Under extremely light traffic conditions, right-of-way might be assigned for a long period of time to the two straight-through traffic phases of one street, for example, phases A1 and A2 of street I, with each interval sequence unit resting in its counter position 5. If there is then received a call for right-of-way from only one conflicting traffic phase such as phase A3, both interval sequence units step sequentially through their positions 6, 7, and 8 to position 9, the transfer position. The odd interval sequence unit associated with phase control unit A3 then steps to its position 1 to assign right-of-way to traffic phase A3. However, there has not been a call for right-of-way on any even traffic phase and so the even interval sequence unit does not have a phase control unit requiring right-of-way. Accordingly, the even interval sequence unit rests in counter position 9, the transfer position. This condition of having right-of-way assigned to only one traffic phase is referred to as single-ended operation as distinguished from double-ended operation in which right-of-way is simultaneously provided to two non-conflicting traffic phases. The phase sequence unit common circuitry of FIG. 8 includes flip-flop 400 which is set to its one condition when single-ended operation results in right-of-way being provided for an even traffic phase but not for an odd traffic phase. Thus, flip-flop 400 is referred to as the odd interval sequence no call flip-flop (ISONCFF), and it provides the signal ISONCFF1 during even phase single-ended operation. Similarly, flip-flop 401 is the even interval sequence no call flip-flop (ISENCFF), and it provides the signal ISENCFF1 during odd phase single-ended operation.

OR gate 405 receives as inputs the one output of the phase next flip-flop 118 in each odd phase control unit. Thus, gate 405 receives as inputs the signals A1PNFF1, B1PNFF1, A3PNFF1, and B3PNFF1. In addition, when the traffic control system is in even phase single-ended operation, OR gate 405 receives as an input the signal ISONCFF1 from the no call flip-flop 400 for the odd interval sequence unit. The output of gate 405 is applied as an input to AND gate 402. The second input to gate 402 is the counter position 6 signal ISO(6) from gate 66 within the odd interval sequence unit. On coincidence of these two inputs to gate 402, the gate generates the signal ISO-PL, causing the odd interval sequence unit to leave its preparatory position. In like manner, OR gate 406 receives as inputs the signals A2PNFF1, B2PNFF1, A4PNFF1, and B4PNFF1 from the phase next flip-flop 118 within each even phase control unit. In addition, OR gate 406 receives the input signal ISENCFF1 during odd phase single-ended operation, when there is no even phase control unit controlling the intersection. The output of gate 406 is connected as an input to AND gate 404. When the counter within the even interval sequence unit is in its position 6, gate 404 receives the ISE(6) signal from AND gate 66 within that even interval sequence unit. On coincidence of these two inputs, gate 406 generates the ISE-PL signal, indicating that the even interval sequence unit is to leave its preparatory position.

The preparatory leave signal PL is applied to OR gate 140 within the gating and timing circuitry of FIG. 5, causing one-shot 154 to generate the advance pulse.

STREET CHANGES

The one output of the phase memory flip-flop 116 associated with each street II traffic phase is applied as an input to OR gate 408, shown in the upper left of FIG. 8. Thus, gate 408 receives the signal A3PMFF1, A4PMFF1, B3PMFF1, and B4PWFF1. The output of gate 408 is the signal "3+4 call." This signal is applied to each set of phase selection circuitry for use as depicted in FIG. 9. In addition, the output of gate 408 is connected to the input of inverter 409 which has its output applied to each set of phase selection circuitry to provide the signal "3+4 call" when there is no input to gate 408.

The output of gate 408 is connected as an input to AND gate 410. Gate 410 also receives as inputs the signals A1PFF1 and ISO(6). Thus, when right-of-way is on phase A1 and the odd interval sequence unit has stepped to its preparatory position, a call for right-of-way from any street II traffic phase results in a signal passing from gate 410 through OR gate 412 to the first input of AND gate 414. AND gate 416 receives as inputs the signals B1PFF1, A1PMFF0, and ISO(6). Thus, if right-of-way is on phase B1 and there has been no call for right-of-way from phase A1, but the odd interval sequence is in its preparatory position, then gate 416 generates a signal which also passes through OR gate 412 to the first input of AND gate 414.

AND gate 418 receives as inputs the signals A2PFF1, ISE(6), and 3+4 call. Therefore, if right-of-way is on traffic phase A2, and there has been a call for right-of-way from a street II traffic phase, and the even interval sequence unit is in its preparatory position, gate 418 passes a signal through OR gate 420 to the second input of AND gate 414. Likewise, AND gate 422 receives as inputs the signals B2PFF1, A2PMFF0, and ISE(6). Therefore, if right-of-way is on traffic phase B2 and there has not been a call for right-of-way from phase A2 but the even interval sequence unit is in its preparatory position, then gate 422 generates a signal which also passes through OR gate 420 to the second input of AND gate 414.

Coincidence of the two inputs to AND gate 414 indicates that right-of-way is on traffic phases found on street I and is about to be transferred to traffic phases of street II. In this condition, gate 414 passes a signal through OR gate 424 which is then applied to OR gate 426. The output of gate 426 is the lock detector signal applied to the vehicle detector DMV 108 via OR gate 248 to the inhibit input of gate 112 within each phase control unit to prevent the output of DMV 108 from passing during the preparatory interval.

The output of OR gate 424 is also applied to the input of time delay 428 which provides a delay in the order of 40 milliseconds. The output of delay 428 is applied to the input of Schmitt trigger 430. The Schmitt trigger 430 output is the signal "street I to street II change." This signal indicates that right-of-way is to be transferred from street I to street II and is applied to each set of phase selection circuitry for use as shown in FIG. 9. Within the phase selection circuitry the street I to street II change signal is utilized to cause the commands which set to the one condition the phase next flip-flop 118 within the appropriate phase control unit, as explained more fully hereinafter with reference to FIG. 9. Time delay 428 is provided to insure that each DMV 108 has locked before the phase selection circuitry decides which phase next flip-flops are to be set.

A corresponding set of circuitry is provided to generate the street II to street I change signal. Thus, OR gate 432 receives as inputs the signals A1PMFF1, A2PMFF1, B1PMFF1, and B2PMFF1 from the phase memory flip-flops within each street I traffic phase control unit. These signals are present whenever a call for right-of-way is received on the associated street I traffic phase. The output of gate 432 is the signal "1+2 call" indicating that a call for right-of-way has been received from one of the street I traffic phases.

This signal is applied to each set of phase selection circuitry for use as depicted in FIG. 9. In addition, the output of gate 432 is connected to the input of inverter 434 which has its output applied to each set of phase selection circuitry. This output is the signal "1+2 call" which is present when there is no input to gate 432.

The output of OR gate 432 is also connected as an input to AND gate 436. Gate 436 also receives as inputs the signals A3PFF1 and ISO(6). Thus, when right-of-way is on traffic phase A3 and a call for right-of-way has been received from one of the street I traffic phases and the odd interval sequence unit is in its preparatory position, gate 436 passes a signal through OR gate 438 to the

first input of AND gate 440. AND gate 442 receives as inputs the signals B3PFF1, A3PMFF0 and ISO(6). Therefore, when right-of-way is on traffic phase B3 and there has not been a call for right-of-way on traffic phase A3, but the odd interval sequence unit is in its preparatory position, gate 442 provides a signal which also passes through OR gate 438 to the first input of AND gate 440.

AND gate 444 receives as input the signals A4PFF1, ISE(6), and 1+2 call. Thus, if traffic phase A4 is providing right-of-way and a call is received for right-of-way from a traffic phase on street I and the even interval sequence unit is in its preparatory position, a signal from gate 444 passes through OR gate 446 to the second input of AND gate 440. AND gate 448 receives as inputs the signals B4PFF1, A4PMFF0 and ISE(6). Therefore, if right-of-way is on traffic phase B4 and there is no call for right-of-way from traffic phase A4, but the even interval sequence unit is in its preparatory position then gate 448 provides a signal which also passes through OR gate 446 to the second input of AND gate 440. Coincidence of these two inputs to gate 440 indicates that right-of-way is on street II and is to be transferred to street I. In this condition, gate 440 provides a signal which passes through OR gate 450 to OR gate 426. The output of OR gate 426 is the lock detector signal which causes the DMV 108 within each phase control unit to lock, as described above.

The output of gate 450 also is connected to the input of time delay 452, which may be in the order of 40 milliseconds. The output of time delay 452 is connected to Schmitt trigger 454 which provides as its output the signal "street II to street I change." This signal is applied to each set of phase selection circuitry for use as depicted in FIG. 9. This signal passes through gating within the phase selection circuitry to cause the appropriate phase next flip-flop to be set to its one condition.

If a single-ended call for right-of-way has been received, then only one phase next flip-flop will be set to its one condition. For example, if right-of-way is on traffic phases A1 and A2 when a call for right-of-way is received from traffic phase A3, then the street I to street II change signal is generated and passes through logic within the odd phase selection circuitry of FIG. 9 to cause the phase next flip-flop within phase control unit A3 to be set to its one condition. As a consequence the signal A3PNFF1 is applied through OR gate 405 to AND gate 402. The ISO(6) signal is also applied to AND gate 402, and so gate 402 generates the signal ISO-PL, causing the counter within the odd interval sequence unit to leave its preparatory position and to commence the vehicle clearance interval of counter position 7. However, since there has not been a call for right-of-way from an even traffic phase, the even phase selection circuitry does not cause any of the phase next flip-flops within the even phase control units to be set to their one condition. Accordingly, there is no signal from any of the phase next flip-flops applied to OR gate 406. In the condition described in the illustrative example above, gate 418 provides a signal through OR gate 420 to one input of AND gate 456. The street I to street II change signal is also applied to gate 456. Since there has not been a call for right-of-way on either phase A4 or phase B4, both the A4PMFF0 signal and the B4PMFF0 signal are applied to gate 456. As a consequence, gate 456 generates a signal which passes through OR gate 458 to set to its one condition ISENCF1. This provides the signal ISENCF1 which passes through OR gate 406 to AND gate 404. Since the even interval sequence unit is in its preparatory position, the signal ISE(6) is also applied to gate 404, and so gate 404 provides the ISE-PL signal, causing the even interval sequence unit to leave its preparatory position, and to enter the vehicle clearance interval of counter position 7.

In like manner, if right-of-way is on street II when a call for right-of-way is received from a single street

I traffic phase, such as traffic phase A1, then the output of gate 446 is applied to the input of AND gate 460. The street II to street I change signal is also applied to gate 460. Since there has not been a call for right-of-way from either phase A2 or phase B2, both the signal A2PMFF0 and the signal B2PMFF0 are applied to gate 460. As a consequence, gate 460 generates a signal which passes through OR gate 458 to the set one input of ISENCF1. Thus, the system is again placed in single-ended operation.

When the system returns to double-ended operation, the even interval sequence unit steps to its counter position 1, and inverter 76 within the even interval sequence unit applies the ISE Σ green signal to the signal input of INHIBITED-AND gate 462. During the preparatory position of the even counter, the ISE(6) signal is applied to the inhibit input of gate 462. Thus, when the green indication is returned to an even traffic phase, gate 462 generates a signal which returns ISENCF1 to its zero condition.

In like manner, when the system is in single-ended operation on an even traffic phase, ISONCF1 is set to its one condition. Thus, the output of OR gate 412 is applied as an input to AND gate 464 which also receives as inputs the signals A3PMFF0, B3PMFF0, and street I to street II change. The output of gate 464 passes through OR gate 466 to the set one input of ISONCF1. Consequently, the signal ISONCF1 passes through OR gate 405 to the first input of AND gate 402, and so when even phase single-ended operation is to take place, this input enables gate 402 to transmit the signal ISO-PL to cause the odd interval sequence unit to leave its preparatory position. The output of OR gate 438 is connected as an input to AND gate 470 which also receives as inputs the signals A1PMFF0, B1PMFF0, and street II to street I change. The output of gate 470 passes through OR gate 466 to cause ISONCF1 to assume its one condition. When double-ended operation is resumed and the green indication is provided for an odd traffic phase, the output of inverter 76 within the odd interval sequence unit is applied as the ISO Σ green signal input to INHIBITED-AND gate 472. During the odd counter position 6 the signal ISO(6) is applied to the inhibit input of gate 472. Thus, when the green indication is returned to an odd traffic phase, the output of gate 472 is applied to the set zero input of ISONCF1 to return the flip-flop to its zero condition.

The transfer from single-ended operation on one street to double-ended operation on the other street requires that the appropriate street change signal be generated. Accordingly, OR gate 474 in FIG. 8 receives as inputs the counter position 9 signals from both the odd interval sequence unit and the even interval sequence unit and applies its output to AND gate 476. OR gate 478 receives the counter position 6 signal from both interval sequence units and applies its output to AND gate 476. OR gate 480 receives the one output from both no call flip-flop; thus it receives as inputs the signals ISONCF1 and ISENCF1. The output of gate 480 is connected to an input of AND gate 476. OR gate 482 receives as inputs the "B/A call" signals from each set of phase selection circuitry. This signal is generated in each set of phase selection circuitry when right-of-way on a left-turn traffic phase is to be terminated and transferred to straight-through traffic from the opposite direction on the same street, as more fully explained hereinafter with reference to FIG. 9.

The output of gate 482 is connected to the input of inverter 484 which has its output tied to an input of AND gate 476. The output of gate 476 is applied as an input of AND gate 486 which also receives as inputs the signals A3PFF0, B3PFF0, A4PFF0, and B4PFF0. Thus, if right-of-way is on a street I traffic phase, these latter four signals are applied to gate 486. During single-ended opera-

tion the interval sequence unit associated with the traffic phases which are not providing any right-of-way is in its counter position 9, and so a signal passes from gate 474 to gate 476. One of the no call flip-flops 400 or 401 is in its one condition, and so a signal passes from gate 480 to gate 476. When the traffic phase which is providing right-of-way reaches its counter position 6, a signal passes from gate 478 to gate 476. If right-of-way is to be transferred to another street, then there is no B/A call signal, and so inverter 484 applies a signal to gate 476. Consequently, gate 476 applies a signal to gate 486, and so gate 486 passes a signal through OR gate 424 to gate 426 to cause the lock detector signal. In addition, this signal passes from gate 424 to time delay 428 which introduces a short delay before turning on Schmitt trigger 430 to generate the street I to street II change signal.

In like manner, the output of gate 476 is applied to gate 488 which receives the signals A1PFF0, B1PFF0, A2PFF0, and B2PFF0 as inputs. Thus, if the system is in single-ended operation on a traffic phase of street II, and it is to change to a street I traffic phase, gate 488 provides a signal which passes through OR gate 450 to gate 426 where it becomes the lock detector signal. In addition, the signal from gate 450 is applied to time delay 452 which introduces a short delay before turning on Schmitt trigger 454 to generate the street II to street I transfer signal.

These street change signals are applied through gates within each set of phase selection circuitry to set to the one condition phase next flip-flop 118 within the appropriate phase control units.

PHASE SELECTION CIRCUITRY—FIGURE 9

FIG. 9 depicts the odd phase selection circuitry within phase sequence unit 30. This odd phase selection circuitry determines which odd traffic phase is next to be assigned right-of-way. A corresponding set of circuits is provided within the even phase selection circuitry to receive the corresponding input signals and to provide the corresponding output signals.

AND gate 502 within the odd phase selection circuitry of FIG. 9, receives as an input the signal B1PFF1 when the phase control unit associated with traffic phase B1 is controlling the intersection. The second input of gate 502 receives the signal A1PMFF1 when a call for right-of-way has been received from traffic phase A1. The last input of gate 502 receives a signal from AND gate 66 within the odd interval sequence unit during odd counter position 6. This signal is designated ISO(6) and exists during the green preparatory period. Thus, gate 502 provides an output during the odd preparatory period when right-of-way is on phase B1 and a call for right-of-way has been received from phase A1. This output from gate 502 passes through OR gate 504 to fire Schmitt trigger 506 which provides the signal A1PNFFS1 that is applied to the set one input of PNFF 118 within the phase control unit associated with traffic phase A1.

In like manner, AND gate 508 receives at its first input the signal B3PFF1 when the phase control unit associated with traffic phase B3 is controlling the intersection. The A3PMFF1 signal is applied to the second input of gate 508 when a call for right-of-way has been received from traffic phase A3. When the odd interval sequence unit is in its green preparatory position of counter position 6, the ISO(6) signal is applied to the third input of gate 508. The output of gate 508 passes through OR gate 510 to fire Schmitt trigger 512 which provides the A3PNFFS1 signal that sets PNFF 118 within the phase control unit associated with traffic phase A3 to its one condition.

The output of gate 502 indicates that right-of-way is to transfer from phase B1 to phase A1, both of which are non-conflicting with phase A2. Similarly, the output of gate 508 indicates that right-of-way is to transfer from

phase B3 to phase A3, both of which are non-conflicting with phase A4. When such a transfer is made in the odd interval sequence unit, no transfer is required on the even traffic phases. Accordingly, the output of AND gate 502 and the output of AND gate 508 are passed through OR gate 513, becoming the signal "B/A call" which is applied to the common phase sequence unit circuitry of FIG. 8.

When the phase control unit associated with traffic phase A1 is controlling the intersection, the signal A1PFF1 is applied to the first input of AND gate 514. The ISO(6) signal is applied to the second input of gate 514 during the preparatory interval of the odd interval sequence unit. If there has not been a call for right-of-way from street II, then the signal 3+4 call is applied to the third input of gate 514. If the odd interval sequence unit has been stepped to its preparatory position while right-of-way is assigned to traffic phase A1 and there has not been a call for right-of-way from street II, then it must be required that right-of-way be transferred to phase B1. Accordingly the output of gate 514 passes through OR gate 516 to fire Schmitt trigger 518, generating the signal B1PNFFS1 which is applied to set one input of PNFF 118 within the phase control unit associated with traffic phase B1.

Similarly, the signal A3PFF1 is applied to the first input of AND gate 520 when phase control unit A3 is controlling the intersection. The ISO(6) signal is applied to the second input of gate 520 during the preparatory interval of the odd interval sequence unit. If there has not been a call for right-of-way on street I, then the signal 1+2 call is applied to the third input of gate 520. Accordingly, gate 520 provides an output when the odd interval sequence unit is in its preparatory interval preparing to transfer right-of-way to another phase and when right-of-way is presently on phase A3, in the absence of a call from street I. This condition means that right-of-way is next to be transferred to phase B3. Accordingly, the output of gate 520 passes through OR gate 522 to fire Schmitt trigger 524, the output of which passes through OR gate 526 to become the signal B3PNFFS1 which is applied to the set one input of PNFF 118 within the phase control unit associated with traffic phase B3. The start signal is also applied to the input of OR gate 526, so that, when the control system is first placed into operation, it commences with the intersection under the control of phase control unit B3.

AND gate 528 receives as its first input the signal A1PMFF1 when a call has been received for right-of-way on the traffic phase A1. The second input to AND gate 528 is the signal B1PMFF0 which is present when there has not been a call for right-of-way on traffic phase B1. When the common portion of the phase control unit depicted in FIG. 8 indicates that right-of-way is to be transferred from street II to street I, an input is applied to the third input of gate 528. On coincidence of these three inputs, gate 528 transmits a signal through OR gate 504 to fire Schmitt trigger 506, thereby generating the signal A1PNFFS1.

The street II to street I change signal is also applied as an input to AND gate 530 which receives as its second input the signal B1PMFF1 when a call for right-of-way has been received from traffic phase B1. Coincidence of these two signals causes gate 530 to transmit a signal through OR gate 516 to fire Schmitt trigger 518 generating the signal B1PNFFS1 which indicates that right-of-way is next to be assigned to phase B1. Thus, phase B1 is given priority over phase A1, and when a street II to street I change is to be made, if a call for right-of-way has been received from traffic phase B1, right-of-way is first assigned to that phase, whether a call has been received from phase A1 or not. However, if no call has been received from phase B1 but a call has been received for right-of-way from phase A1, then right-of-way is assigned to phase A1.

Similarly, AND gate 532 receives as its first input the signal A3PMFF1, as its second input the signal

B3PMFF0

and as its third input the street I to street II change signal provided by the common phase sequence unit circuitry of FIG. 8. On coincidence of these three signals gate 532 passes a signal through OR gate 510 to fire Schmitt trigger 512, thereby generating the signal A3PNFFS1 which indicates that right-of-way is next to be assigned to phase A3. AND gate 534 receives as its first input the street I to street II change signal and as its second input the signal B3PMFF1. Gate 534 passes its output through OR gate 522 to fire Schmitt trigger 524 which indicates that right-of-way is next to be assigned to traffic phase B3. Hence, when the street I to street II change signal indicates that right-of-way is to be transferred to street II, and a call for right-of-way has been received from traffic phase B3, that traffic phase is next assigned right-of-way, whether a call has been received from phase A3 or not. But, in the absence of a call for right-of-way from phase B3 and in the presence of a call for right-of-way from phase A3, then phase A3 is next assigned right-of-way.

TRANSFER GATING CIRCUITRY—FIGURE 10

Phase sequence unit 30 includes two sets of gating circuitry which generate the transfer commands for the two interval sequence units. FIG. 10 depicts the circuitry which generates the signal ISO-TR to cause the odd interval sequence unit to transfer control of the intersection from one odd phase control unit to another. A corresponding set of gating generates the transfer signal ISE-TR for the even interval sequence unit.

OR gate 536 in FIG. 10 receives as inputs the signals A1PNFF1 and B1PNFF1 when either Schmitt trigger 506 or Schmitt trigger 518 of FIG. 9 has caused the phase next flip-flop PNFF 118 of phase A1 or PNFF 118 of phase B1 respectively, either of which is illustrated in FIG. 4, to set to its 1 condition. This output from gate 536 is applied as an input to AND gate 538. Gate 538 also receives as inputs the signals A4PFF0 and B4PFF0 to indicate that the phase control units associated with traffic phases A4 and B4 are not controlling the intersection. In like manner the signal A3PNFF1 and the signal B3PNFF1 are applied as inputs to OR gate 540 when the phase next flip-flop in the phase control unit associated with either phase A3 or phase B3, respectively, is in its one condition. The output of gate 540 is connected to one input of AND gate 542 which receives at its other inputs the signals A2PFF0 and B2PFF0 when phase control units A2 and B2 are not controlling the intersection. The outputs of the gates 538 and 542 pass through OR gate 544 to one input of AND gate 546. The other input of gate 546 is connected to the output of gate 72 associated with the counter of the odd interval sequence unit, shown in FIG. 3. This signal ISO(9) indicates that the counter within the odd interval sequence unit is in its transfer position 9.

The phase next flip-flop 118 (FIG. 4) within the phase control unit of the traffic phase which is to be assigned right-of-way is set to its one condition during the preparatory interval of counter position 6. During the transfer interval of counter position 9, the phase flip-flop 120 within each phase control unit is set to its zero condition. Accordingly, during counter position 9, the signals A2PFF0, B2PFF0, A4PFF0, and B4PFF0 are all present. If for example, the right-of-way has been called to phase A3, then the phase next flip-flop 118 within the phase control unit associated with traffic phase A3 is set to its one condition, and so the signal A3PNFF1 passes through OR gate 540 (FIG. 10) to AND gate 542. As a consequence, gate 542 passes its output through gate 544 to one input of AND gate 546. Thus, when the ISO(9) signal is applied to gate 546, this gate generates the transfer signal for the odd interval sequence unit, referred to as signal ISO-TR. This transfer signal is applied

to gates 140 and 166 within the gating and timing circuitry associated with the odd interval sequence unit, as shown in FIG. 5. As a consequence, the odd interval sequence unit generates an advance pulse to step its counter to position 1, thereby initiating the control period for phase control unit A3. The even phase selection circuitry of the phase sequence unit 30 contains corresponding gates which under corresponding conditions provide the ISE-TR signal which is applied to the even interval sequence unit to step that counter from its transfer position 9 to its skip position 1.

If a call for single ended operation is received, only one transfer signal is generated. For example, if a call for even phase single ended operation is received, no odd phase next flip-flop set one signal is generated. Accordingly, neither OR gate 536 nor OR gate 540 provides an output. Consequently, gate 546 cannot transmit the ISO-TR signal, and so the odd interval sequence unit rests in its counter position 9, causing red indications on all of its traffic phases, while the even interval sequence unit steps through its regular sequence. When this happens the odd no call flip-flop ISONCFF, within the common circuitry of the phase sequence unit, is set to its one condition, providing the signal ISONCFF1, as depicted in FIG. 8.

TRANSFER FROM SINGLE-ENDED TO DOUBLE-ENDED OPERATION ON THE SAME STREET—FIGURE 9

When the traffic control system is operating in even phase single ended operation and a call for right-of-way is received from a non-conflicting traffic phase on the same street, AND gate 548 provides a pulse which is passed through appropriate gating circuitry to fire the appropriate Schmitt trigger 506, 512, 518, or 524 which generates a signal to set the phase next flip-flop 118 in the phase control unit to which right-of-way is to be called. The first input to gate 548 is applied from OR gate 550 which receives as inputs the signals from the memory flip-flops of the odd traffic phases. Thus the signals A1PMFF1, B1PMFF1, A3PMFF1, and B3PMFF1 are applied as inputs to gate 550, and whenever a call is present for right-of-way on one of the odd traffic phases, gate 550 applies an input to AND gate 548. The signal A2PFF1 is applied as an input to OR gate 552 which receives as its other input the signal B2PFF1. Thus whenever either phase control unit A2 or phase control unit B2 is controlling the intersection, a signal passes from OR gate 552 to the first input of AND gate 554.

The signals A2PNFF1 and B2PNFF1 are provided as inputs to OR gate 556. The output of gate 556 is connected to the second input of AND gate 554. Gate 554 has its output connected through OR gate 558 to one signal input of INHIBITED-AND gate 560. The second signal input of gate 560 receives the signal ISONCFF1 during even phase single ended operation. The even interval sequence unit advance pulse is applied to the inhibit input of gate 560 so that during this advance pulse gate 560 cannot permit passage of its output signal.

INHIBITED-AND gate 562 receives the Σ green signal from inverter 76 within the even interval sequence unit. The inhibit input of gate 562 receives the counter position 6 signal from gate 66 within the even interval sequence unit. Therefore, gate 562 provides an output signal during counter positions 1-5 of the even interval sequence unit. This output from gate 562 is connected as an input to OR gate 558.

In a similar manner, OR gate 564 receives as inputs the signals A4PFF1 and B4PFF1 and applies its output to one input of AND gate 566. OR gate 568 receives as inputs the signals A4PNFF1 and B4PNFF1 and provides its output to the second input of gate 566. The output of gate 566 is connected as an input of OR gate 558.

During even phase single ended operation, the signal ISONCFF1 is applied as an input to INHIBITED-AND

gate 560 to enable gate 560, except when the even interval sequence unit advance pulse is applied to the inhibiting input of the gate. During positions 1-5 of the even interval sequence unit counter, a signal passes from gate 562 through gate 558 to gate 560, causing gate 560 to apply an enabling input to AND gate 548. If a call for right-of-way on one of the odd traffic phases is present during this time, a signal from OR gate 550 is applied to the second input of gate 548. The output from gate 548 is then applied as an input to each of the AND gates 570, 572, 574, and 576. If, for example, phase B1 has received the call for right-of-way, then the signal B1PMFF1 is applied as an input to gate 572. The output of gate 552, which in the event of a call for phase B1 must be the signal A2PFF1, is applied as the third input to gate 572, causing gate 572 to transmit a signal through OR gate 516 to fire Schmitt trigger 518 which generates the B1PNFFS1 signal to set the phase next flip-flop 118 within phase control unit B1. As a consequence, the B1PNFF1 signal from flip-flop 118 within the B1 phase control unit passes through OR gate 536 (FIG. 10) to AND gate 538. Since phase A2 is in control of the intersection, gate 538 is enabled to pass a signal through OR gate 544 to gate 546. The odd interval sequence unit is resting in its counter position 9, and so gate 546 generates the odd interval sequence unit transfer signal to cause an advance pulse within the odd interval sequence unit, thereby stepping its counter to position 1 to provide right-of-way for phase B1.

If instead a call for right-of-way has been received from phase A1, then that call signal A1PMFF1 passes through gates 550 and 548 to gates 570-576. The A1PMFF1 signal is also applied to gate 570. If no call has been received for right-of-way on phase B1, then gate 570 also receives the input signal B1PMFF0. The output of gate 552 is also applied to gate 570, and so gate 570 sends a signal through OR gate 504 to fire Schmitt trigger 506 which generates the signal A1PNFFS1 to set its one condition the phase next flip-flop 118 within phase control unit A1. Since the signal B1PMFF0 is required for this, but no A1 signal is required for gate 572, phase B1 is given preference over phase A1, just as in the case of a street II to street I transfer, as described above.

In like manner, calls for phase A3 or phase B3 can be accommodated when the even interval sequence unit is controlling the intersection in single ended operation of phase A4 or phase B4. Since there is a conflict between phases A2 and A3, phases A2 and B3, phases B2 and A3, and phases B2 and B3, the gating circuitry insures that single ended operation can not be transferred to double-ended operation for conflicting phases. When one of the gates 570-576 provides a signal to its associated Schmitt trigger, a signal is also passed through OR gate 578 which indicates that the vehicle detectors associated with each phase control unit are to be locked. This signal is applied through OR gate 426 in the common section of the phase sequence unit and then becomes the lock detector signal applied to DMV 108 within each phase control unit.

GENERATION OF CALL AWAY SIGNAL— FIGURE 9

When a call for right-of-way is received on a traffic phase which conflicts with one of the traffic phases presently providing right-of-way, and which is assigned to the same interval sequence unit, for example a call for right-of-way on traffic phase A3 while right-of-way is provided on phase A1, the Σ no call signal for that interval sequence unit is terminated, as explained above. In the event that right-of-way is provided on a traffic phase and a call for right-of-way is received from a conflicting traffic phase assigned to the other interval sequence unit, for example a call for right-of-way on traffic phase A4 while right-of-way is assigned to traffic phase A1, the signal "call away" is generated. Thus, the

output of OR gate 552 is applied to one input of AND gate 580. OR gate 582 receives as inputs the signals A3PMFF1 and B3PMFF1, and the output of gate 582 is connected to the second input of gate 580. Phase A3 conflicts with both phases A2 and B2, and phase B3 conflicts with both phases A2 and B2. Thus, when right-of-way is on either phase A2 or phase B2 and a call for right-of-way on a conflicting odd phase is received, there are signals applied to the two inputs of gate 580, and so gate 580 passes a signal through OR gate 584 which becomes the even interval sequence unit call away signal.

In like manner, OR gate 564 receives the input signals A4PFF1 and B4PFF1 and provides an output which is connected to the first input of AND gate 586. OR gate 588 receives as inputs the signals A1PMFF1 and B1PMFF1 and applies its output to the other input of gate 586. Phase A1 conflicts with both phases A4 and B4, and phase B1 conflicts with both phases A4 and B4. Thus, when right-of-way is on either phase A4 or phase B4 and a call for right-of-way is received from a conflicting odd traffic phase, signals are applied to the two inputs of gate 586, and gate 586 provides an output which passes through OR gate 584 to become the signal ISE call away. This ISE call away signal is applied to gates 177 and 256 within the gating and timing circuitry of the even interval sequence unit, as depicted in FIG. 5.

HOLD-GATING CIRCUITRY—FIGURE 11

In the event that right-of-way is, for example, on traffic phases A1 and B2 of street I, providing right-of-way for the east-bound straight-through traffic and for the west-bound left-turn traffic becoming south-bound, when a call for right-of-way is received from phase A2, the east-bound straight-through traffic phase, followed by a call for right-of-way on one or more of the street II north-bound or south-bound traffic phases, the west-bound straight-through traffic phase A1 is prevented from proceeding to its preparatory condition until right-of-way has been transferred from phase B2 to phase A2, and until the right-of-way interval for phase A2 has reached its vehicle interval of counter position 5. Corresponding provisions are made for the other combinations of traffic phases. These are achieved by means of the hold circuitry included in FIG. 11. Assume, for example, that right-of-way is assigned to traffic phases A1 and B2. Then the signal B2PFF1 passes through OR gate 590 in FIG. 11 to the first input of AND gate 592. If a call for right-of-way is received from traffic phase A2, then the signal A2PMFF1 is applied as an input to gate 592. In the event of a call for right-of-way from one of the street II traffic phases, the signal "3 + 4 call" is applied to the third input of gate 592. On coincidence of these three signals at the inputs of gate 592, the gate applies an output which passes through OR gate 594 to become the phase A1 hold signal. In the event that there is no call for right-of-way on phase A1, then the signal A1PMFF0 is applied as an input to gate 596, which receives the output of gate 592 at its second input. In this condition, gate 596 applies a signal through OR gate 598 to become the phase B1 hold signal. The outputs of gates 64 and 66 associated with the counter within the even interval sequence unit are applied as inputs to OR gate 600 during counter positions 5 and 6. The output of gate 600 is connected as an input to inverter 602 which applies its output to OR gate 590. Thus, in the conditions described in the illustrative example where right-of-way is on phase A1 and phase B2, when a call for right-of-way is received from phase A2 and a call for right-of-way is received from one of the conflicting street II traffic phases, gate 592 generates a signal which becomes the A1 hold signal. This A1 hold signal is applied to one input of AND gate 120' within the A1 phase control unit. Since phase control unit A1 is controlling

the intersection at the time, the signal A1PFF1 is also applied to that gate 120', and the gate passes the signal to the Σ hold circuitry. In the gating and timing circuitry of FIG. 5 the Σ hold signal is applied to the inputs of OR gate 258 and OR gate 259. The output of OR gate 259 is applied to the inhibit input of gate 181, thus blocking the maximum timer signal which otherwise would pass through gate 181 to cause the counter to step to its preparatory position. The output of gate 258 is connected to one input of AND gate 254. The counter position 5 signal passes through gates 250 and 252 to the other input of 254. Therefore the output of gate 254 blocks gate 150 so that no signal can be applied to one shot 154, preventing generation of an advance pulse. This hold signal continues until the even interval sequence unit has stepped to its counter position 5 for phase A2. So long as the hold signal continues, the odd counter cannot be stepped to its next position.

In like manner, OR gate 604 (FIG. 11) passes the output of inverter 602 to one input of AND gate 606. In addition, gate 604 passes the signal B4PFF1 to gate 606. AND gate 606 also receives as inputs the signals A4PMFF1 and 1 + 2 call. On coincidence of these three inputs to gate 606, the gate passes a signal through OR gate 608 to provide the A3 hold signal. AND gate 610 receives at its first input the output of gate 606 and at its other input the signal A3PMFF0. The output of gate 610 passes through OR gate 612 to become the B3 hold signal. OR gates 594, 598, 608, and 612 are provided to permit the application of an external hold command for any traffic phase, as depicted in FIG. 11.

The above description of phase selection circuitry, the transfer gating circuitry, and the hold gating circuitry of FIGS. 9-11 respectively has made reference to the odd traffic phases and the odd interval sequence unit. A corresponding set of circuitry is provided for the even traffic phases and the even interval sequence unit. Thus, in FIGS. 9-11, if corresponding phase A1 signals and phase A2 signals are interchanged, corresponding phase B1 signals and phase B2 signals are interchanged; corresponding phase A3 signals and phase A4 signals are interchanged, corresponding phase B3 signals and phase B4 are interchanged, and corresponding ISO signals and ISE signals are interchanged, then the FIGS. 9-11 depict the corresponding circuitry for use with the even traffic phases and with the interval sequence unit.

OPERATION OF THIS EMBODIMENT

Within the circuitry of the present invention numerous combinations of signals might be encountered during the transfer of right-of-way from one set of traffic phases to another set of traffic phases, and the particular combination found during any one transfer depends upon which set of traffic phases is providing right-of-way and which set of traffic phases is next to provide right-of-way. Right-of-way transfer can be adequately illustrated by a few typical examples.

INTERVAL SEQUENCE OPERATION

Assume that right-of-way has just been transferred to traffic phases A1 and A2 and that the counter in both the odd interval sequence unit and the even interval sequence unit is in its position one, the green skip position. In this situation, and gate 56 (FIG. 3) within each interval sequence unit applies its counter position one signal through the OR gate 140 (FIG. 5) of that interval sequence unit. From there, the signal passes through gate 141 to turn on Schmitt trigger 142. This fires DC DMV 144, passing a signal through gates 148, 150, and 152 to trigger one-shot 154, thereby generating an advance pulse. If a pedestrian call has been received on the traffic phase, the Σ ped call signal passes through gate 78 (FIG. 3) to block gate 79. Consequently, the advance pulse passes through gate 80 to step the counter to its position 2. This

action takes place in each interval sequence unit, provided that a pedestrian push-button has been actuated on each traffic phase. During counter position 2, the output from the gate 58 within the interval sequence unit assigned to traffic phase A1 counter circuit (FIG. 3) is applied to resistor 121 within the associated phase control unit (FIG. 4). As a consequence, current passes through resistor 121 and OR gate 126 to capacitor 127. The voltage on capacitor 127 is applied through diode 134 to OR gate 140 within the gating and timing circuitry of the associated interval sequence unit (FIG. 5). Thus, the odd interval sequence unit counter position 2 signal is tied to resistor 121 within phase control unit A1, and diode 134 of unit A1 is connected to OR gate 140 of the odd interval sequence unit. Corresponding connections are present between the even interval sequence unit and phase control unit A2.

Within each interval sequence unit the output of gate 140 passes through gate 141 to Schmitt trigger 142. When the voltage on capacitor 127 has reached the firing level of Schmitt trigger 142, the Schmitt trigger turns on to again cause an advance pulse which passes through gate 80 to step the counter to its position 3, the pedestrian clearance interval. The advance pulse also passes through OR gate 156 (FIG. 5) to become the interval timer reset signal which is applied through OR gate 130 (FIG. 4) to gating amplifier 132 to discharge capacitor 127. Since each phase control unit has its own variable resistor 121, the pedestrian right-of-way interval can have a different duration for each traffic phase. Thus the pedestrian right-of-way interval might last for different periods of time for phase A1 and for phase A2.

In like manner, during counter position 3, voltage passes through variable resistor 122 and OR gate 126 to capacitor 127 within phase control units A1 and A2. When the voltage on capacitor 127 again reaches the firing level of Schmitt trigger 142, the Schmitt trigger turns on, again causing an advance pulse. This time, however, the counter position 3 signal from gate 60 is applied through OR gate 90 (FIG. 3) to block gate 80 and is applied to gate 81. Therefore, the advance pulse cannot pass directly to the counter, but instead it passes through gates 81, 82, and 84 to set the counter to its position 5. Thus, position 4 is omitted when a pedestrian interval is provided. Position 5 is the green vehicle interval during which time the pedestrian indicators provide wait or don't walk indications. Again, since each phase control unit contains a variable resistor 122, the duration of the pedestrian clearance interval may be different for each traffic phase. Consequently, one traffic phase may reach its vehicle interval before the other one.

During the vehicle interval, the counter position 5 signal is applied through resistor 182 to capacitor 183 and through resistor 210 to capacitor 212, within the phase control unit (FIG. 4). In addition, the counter position 5 signal is applied through resistor 194 to capacitor 196 within the gap measurement timer of FIG. 6. If there has not been a call for right-of-way from a traffic phase conflicting with phases A1 and A2, then the signal Σ no call is applied to the signal input of gate 205 and the call away signal is not blocking gate 205. Therefore, gate 205 produces an output which is applied through gate 206 to turn on the gating amplifier 208. Similarly, gate 213 (FIG. 4) produces an output which passes through gate 214 to turn on gating amplifier 215. As a consequence, capacitors 196 and 212 are clamped to ground, preventing the build-up of voltage on these capacitors. Each time another vehicle crosses the detection zone of the vehicle detector on a phase which has right-of-way, a signal is applied from DMV 108 within the phase control unit associated with that traffic phase through OR gate 110 and INHIBITED-AND gate 186 to turn on gating amplifier 185. Thus, with each vehicle passing the detector, the capacitor 183 within the vehicle timing circuitry of that traffic phase is discharged. In addition,

the pulse from gate 110 passes through OR gate 226 to turn on gating amplifier 228. This discharges capacitor 224 within the passage timer associated with that traffic phase.

When a call for right-of-way is received from a conflicting traffic phase, then the outputs from gates 205 and 213 terminate. As a consequence, gating amplifiers 208 and 215 turn off, and so voltage commences to build up on capacitors 196 and 212. Each time a vehicle passes the vehicle detector on the traffic phase having right-of-way, the pulse from DMV 108 passes through OR gate 110 (FIG. 4) and AND gate 209 to become the Σ gap reset signal which passes through gate 206 (FIG. 6) to turn on gating amplifier 208. Hence, with each vehicle passing the detector, capacitor 196 is discharged. Thus, after a conflicting call for right-of-way has been received, and the phase with right-of-way has reached its vehicle interval, the voltage on capacitor 196 indicates the gap between consecutive vehicles on the traffic phase having right-of-way. The voltage on capacitor 212 represents the length of time which a vehicle on a conflicting traffic phase has been waiting for right-of-way. These voltages are applied through impedance converters 198 and 217 to resistors 200 and 218. The voltage at junction 202, which is the sum of the voltages on capacitors 196 and 212, is applied to the input of Schmitt trigger 204. Thus, if the gap between consecutive vehicles reaches such a duration that the voltage on capacitor 196 rises to a critical level, Schmitt trigger 204 turns on. This critical level is continuously reduced as a function of the length of time that a vehicle has been waiting for right-of-way on a conflicting traffic phase. Once the gap reaches the critical level, Schmitt trigger 204 turns on to set flip-flop 220.

The one output of flip-flop 220 is the last vehicle passage (LVP) signal. This LVP signal blocks gate 186 within the phase control units (FIG. 4) so that subsequent vehicle actuations do not discharge capacitor 183. Consequently, the voltage on capacitor 183 increases. Resistor 182 is set to a value which permits sufficient time to elapse during the build-up of voltage on capacitor 183 for the last vehicle which caused discharge of capacitor 183 to travel from the vehicle detector through the intersection. When the voltage on capacitor 183 has reached the proper level, it turns on Schmitt trigger 190 within the gating and timing circuitry of FIG. 5. As a consequence, a signal passes through gates 192, 140 and 141 to fire Schmitt trigger 142, thereby causing an advance pulse which steps the counter to its position 6.

In the event that traffic on the phase having right-of-way is so heavy that the voltage on capacitor 196 never reaches the firing level of Schmitt trigger 204, the voltage on capacitor 170 within the maximum timer circuit of the phase control unit of FIG. 4 increases until it reaches the firing level of Schmitt trigger 178 within the interval sequence unit of FIG. 5. This Schmitt trigger output turns on DC DMV 180, the output of which passes through gate 181 to become the signal to step the counter to its preparatory position. The output from gate 181 is applied to line 181' in FIG. 3 from which it sets the counter to its position 6, the green preparatory interval. Thus, the counter moves out of the vehicle interval of position 5 either when the gap between consecutive vehicles is in excess of a critical level or after a vehicle has been waiting for right-of-way on a conflicting traffic phase for a maximum period of time.

TRANSFER FROM PHASES A1 AND A2 TO PHASES B3 AND B4 AND THEN TO PHASES A3 AND A4—LEFT-TURN PHASES

Counter position 6 is the preparatory interval during which phase sequence unit 30 determines which traffic phase is next to be assigned right-of-way. Assume that, while right-of-way is on phases A1 and A2, calls for right-of-way are received from traffic phases A3, B3, A4, and B4, the north-bound and south-bound straight-

through and left-turn traffic phases. Gate 552 of the odd phase selection circuitry depicted in FIG. 9 passes the A2PFF1 signal to one input of gate 580. The signals A3PMFF1 and B3PMFF1 pass through gate 582 to the other input of gate 580. As a consequence, gate 580 passes a signal through OR gate 584 to become the ISE call away signal. This signal is utilized within the even interval sequence unit to initiate the termination of the vehicle interval, in the event the call for right-of-way on phase A3 or B3 is received before the call for right-of-way on phase A4 or B4.

Within the phase sequence unit common circuitry of FIG. 8, the signals A3PMFF1, A4PMFF1, B3PMFF1, and B4PMFF1 are applied to OR gate 408 thereby generating the 3+4 call signal which is applied to one input of AND gate 410. Gate 410 also receives the signal A1PFF1, and, when the odd interval sequence unit is in its preparatory interval, gate 410 receives the ISO6 signal. As a consequence, an output from gate 410 passes through gate 412 to one input of AND gate 414. Gate 418 receives the inputs A2PFF1 and 3+4 call. When the even interval sequence unit has stepped to its preparatory interval, the signal ISE6 is applied to gate 418, and as a consequence, an output from gate 418 passes through OR gate 420 to the second input of gate 414. Thus, when both interval sequence units have reached their preparatory position, gate 414 passes a signal through OR gates 424 and 426 to lock the detector DMV 108 within each phase control unit. In addition, this output from gate 424 is applied to time delay 428 which times a very brief interval before turning on Schmitt trigger 430 to generate the street I to street II change signal which is applied to both the odd phase selection circuitry and the even phase selection circuitry of FIG. 9.

Within the odd phase selection circuitry shown in FIG. 9, the street I to street II change signal is applied as an input to AND gate 534 which also receives the B3PMFF1 signal from the memory flip-flop within phase control unit B3. As a consequence, gate 534 passes a signal through OR gate 522 to trigger Schmitt trigger 524, the output of which passes through gate 526 to become the B3PNFFS1 signal that is applied to set to its one condition the phase next flip-flop 118 within phase control unit B3. In like manner, the street I to street II change signal and the B4PMFF1 signal pass through gating within the even phase selection circuitry to generate the B4PNFFS1 signal which sets to its one condition the PNFF 118 within phase control unit B4. Thus, the B phases, associated with the left-turn traffic, are given right-of-way before the A phases of the straight-through traffic.

When PNFF 118 within phase control unit B3 is in its one condition, the signal B3PNFF1 passes through OR gate 405 to one input of AND gate 402 within the phase sequence unit common circuitry of FIG. 8. In like manner, the signal B4PNFF1 passes through gate 406 to one input of gate 404. Since the interval sequence units are in their preparatory position, the signals ISO(6) and ISE(6) are applied to gates 402 and 404, respectively. As a consequence, gate 402 generates the signal ISO-PL which is applied to OR gate 140 within the gating and timing circuitry of the odd interval sequence unit, as depicted in FIG. 5. This causes an advance pulse which steps the counter within the odd interval sequence unit to its position 7, the vehicle clearance position. Similarly, the ISE-PL signal causes the advance pulse within the even interval sequence unit, stepping it to its clearance position. Within the phase control units A1 and A2, voltage is applied through variable resistor 124 and OR gate 126 to capacitor 127 during the vehicle clearance interval. When the voltage on capacitor 127 reaches the firing level of Schmitt trigger 142 (FIG. 5), the clearance interval ends, and the advance pulse steps the counter 75 to its position 8, the all-red interval. The interval timer

reset signal then causes capacitor 127 to be discharged, and voltage is applied through variable resistor 125 and OR gate 126 to again build up voltage on capacitor 127. Following timing of the all-red interval, Schmitt trigger 142 again fires, causing another advance pulse which steps the counter to its position 9, the transfer position. The counter position 9 signal resets the phase flip-flop PFF 120 to its zero condition (FIG. 4). Within the transfer gating circuitry of FIG. 10, the ISO(9) signal is applied as an input to AND gate 546. The signal B1PNFF1 passes through OR gate 536 to one input of AND gate 538. Gate 538 also receives the signals A4PFF0 and B4PFF0 and passes an output through OR gate 544 to the second input of AND gate 546. Coincidence of the two inputs to gate 546 causes that gate to generate the signal ISO-TR which indicates that transfer is to be made on an odd traffic phase. The ISO-TR signal is applied to OR gate 140 within the gating and timing circuitry of the odd interval sequence unit as depicted in FIG. 5. As a consequence, another advance pulse is generated, returning the counter to its one position. Within phase control unit B3 the signal B3PNFF1 is applied to AND gate 119. During counter position one, gate 119 receives a second input, and it generates an output which sets the PFF 120 within phase control unit B3 to its one condition. Therefore, right-of-way has been transferred to phase B3. In like manner, the transfer gating circuitry within the even interval sequence unit generates the even transfer signal ISE-TR which causes an advance pulse within the even interval sequence unit to step its counter to the one position, thereby transferring right-of-way to traffic phase B4.

Since there are no pedestrian functions associated with the B traffic phases, the counter position 1 signal passes through gates 79 and 90 to block gate 80 and to enable gate 96 (FIG. 3), within the interval sequence units. The advance pulse then is applied to gate 96, causing gate 96 to pass a pulse through gates 84 and 98 to set the counter to its position 4, the green initial interval. Similarly, on an A traffic phase, if there are no pedestrian calls, counter positions 2 and 3 are omitted. The counter within each of the interval sequence units then steps through its position 4 to its position 5 as timed by resistor 123. Since the calls for right-of-way which were received from traffic phases A3 and A4 during phases A1 and A2 right-of-way have not yet been filled, the gap timing circuitry and maximum timing circuitry is operating in both interval sequence units during this position 5 vehicle interval.

Within the phase selection circuitry of FIG. 9 the signal B3PFF1 and A3PMFF1 are applied to AND gate 508. When the odd interval sequence unit reaches its preparatory position, the signal ISO(6) is also applied to gate 508 causing the gate to transmit a signal through OR gate 510 to fire Schmitt trigger 512, generating the A3PNFF1 signal which sets to its one condition the phase next-flip-flop 118 within phase control unit A3. In like manner, within the even phase selection circuitry the signals B4PFF1, A4PMFF1, and ISE(6) result in the generation of the A4PNFF1 signal which sets to its one condition the phase next flip-flop 118 within the phase control unit A4.

The A3PNFF1 signal passes through OR gate 405 within the phase sequence unit common circuitry of FIG. 8 to the first input of gate 402. Since the odd interval sequence unit is in its preparatory position, the signal ISO(6) is also applied to gate 402, and so the gate generates the ISO-PL signal causing the odd interval sequence unit to leave its preparatory position. This signal passes through gate 140 within the gating and timing circuitry (FIG. 5) associated with the odd interval sequence unit, causing an advance pulse which steps the odd counter to its position 7, the vehicle clearance position. Similarly, the A4PNFF1 signal passes through OR

gate 406 and AND gate 404 to cause the signal ISE-PL which results in an advance pulse within the even interval sequence unit stepping the even counter to its vehicle clearance position.

Following timing of the two vehicle clearance intervals, the two interval sequence units step to the all-red position. Following that, they step to the transfer position, and the transfer gating circuitry of FIG. 10 causes the transfer signal to generate another advance pulse which returns the counters to their position 1 and which transfers right-of-way to traffic phases A3 and A4.

The timing and gating circuitry of FIG. 5, the phase selection circuitry of FIG. 9, and the gating within the phase sequence unit common circuitry of FIG. 8 operate independently for the odd traffic phase and for the even traffic phase in this sequence. Thus, if more left-turn traffic exists on one of the phases than on the other, for example if more cars are turning left on phase B3 than on phase B4, the even interval sequence unit may leave its vehicle interval before the odd interval sequence unit leaves its vehicle interval. This would be due to the occurrence of a gap greater than the critical gap length in the traffic on phase B4. Should this happen, the even interval sequence unit would step through its clearance, all-red, and transfer positions to bring right-of-way to traffic phase A4, while right-of-way still remains on traffic phase B3. Since phases A4 and B3 are non-conflicting, it is not necessary that the two transfers be made simultaneously. When the transfer of right-of-way results in a street change, the ISO-PL signal and the ISE-PL signal (FIG. 8) occur simultaneously, and the ISO-TR signal and the ISE-TR signal (FIG. 10) occur simultaneously. Thus, both right-of-way transfers occur together.

35 TRANSFER FROM PHASES A3 AND A4 TO PHASES A1 AND B2—ONLY ONE LEFT-TURN PHASE

When control of the intersection is transferred to phase control units A3 and A4, whether simultaneously or sequentially, the two interval sequence units then start a new cycle of operation. If there has been a call for pedestrian right-of-way, the counters step through their counter positions 1, 2 and 3 to position 5. If there has not been a pedestrian call, the counters step through their positions 1 and 4 to position 5. The counter within each interval sequence unit operates in response to pedestrian calls on its associated traffic phase before coming to rest in position 5, the vehicle interval.

Assume that next there is a call for right-of-way from traffic phases A1 and B2. The B1PMFF1 signal and the A4PFF1 signal pass through gates 588 and 564 (FIG. 9) respectively to gate 586 where they cause a signal to be applied to OR gate 584 to become the ISE call away signal. The A1PMFF1 signal and B2PMFF1 signal pass through OR gate 432 (FIG. 8) to become the 1+2 call signal which is applied to gate 436. Gate 436 also receives the input A3PFF1, and, during the odd interval sequence unit preparatory interval, the signal ISO(6) is applied to gate 436. As a consequence, gate 436 transmits an output through OR gate 438 to one input of AND gate 440. The 1+2 call signal is also applied to gate 444 which receives as another input the signal A4PFF1. When the even interval sequence unit is in its preparatory position, gate 444 receives the input ISE(6). As a consequence, gate 444 transmits a signal through OR gate 446 to the second input of AND gate 440. Thus, when both interval sequence units have reached their preparatory positions, gate 440 transmits a signal through OR gate 450 and OR gate 426 to lock the detector DMV 108 within each phase control unit. This signal out of gate 450 is also applied to time delay 452 which introduces a short delay before turning on Schmitt trigger 454 to cause the street II to street I change signal.

Within the odd phase selection circuitry of FIG. 9, the street II to street I change signal is applied to gate 528

which also receives the A1PMFF1 signal and the B1PMFF0 signal. As a consequence, gate 528 passes a signal through OR gate 504 to fire Schmitt trigger 506, generating the A1PNFFS1 signal which sets to its one condition the phase next flip-flop 118 within phase control unit A1. Within the even phase selection circuitry the B2PMFF1 signal, and the street II to street I change signal, pass through gating corresponding to gates 530 and 516, to cause the generation of the B2PNFFS1 signal which sets to its one condition the phase next flip-flop 118 within phase control unit B2. Once again, AND gates 402 and 404 within the phase sequence unit common circuitry generate the ISO-PL signal and the ISE-PL signal, respectively, causing the interval sequence units to leave their preparatory position. Hence, each interval sequence unit steps through its vehicle clearance interval and its all-red interval to its transfer position. Within each set of phase selection circuitry the transfer gating depicted in FIG. 10 results in the generation of the transfer signals; thus each interval sequence unit is returned to its counter position one and right-of-way is transferred to phases A1 and B2.

TRANSFER FROM PHASES A1 AND B2 TO PHASES A1 AND A2 AND THEN TO PHASES A3 AND A4—THE HOLD CIRCUITRY

Assume that next a call for right-of-way is received from traffic phase A2 followed by calls for right-of-way from traffic phases A3 and A4. Within the odd hold gating circuitry of the phase sequence unit 30, depicted in FIG. 11, the signal B2PFF1 passes through OR gate 590 to one input of AND gate 592. Since right-of-way has been called for phase A2, the signal A2PMFF1 is also applied to gate 592. The call for right-of-way from phases A3 and A4 passes through OR gate 408 in FIG. 8 to become the 3+4 call signal which is also applied to gate 592. As a consequence, gate 592 applies a signal through OR gate 594 which becomes the phase A1 hold signal. This signal is connected to one input of AND gate 120' within phase control unit A1.

Gate 120' applies the Σ hold signal to OR gate 258 within the gating and timing circuitry of the odd interval sequence unit, as depicted in FIG. 5. In counter position 5 of the odd interval sequence unit a signal passes through gates 250 and 252 to the second input of gate 254. Therefore gate 254 blocks gate 150 so that no signal can be applied to the input of one-shot 154, and so the advance pulse for the odd interval sequence unit cannot be generated. In addition, the hold signal passes through OR gate 259 to block gate 181 so that the maximum timer cannot cause the counter within the odd interval sequence unit to step to its preparatory position.

The hold signal is also applied to the inhibit input of gate 219 (FIG. 6) to prevent flip-flop 220 from setting to its one condition. Thus, the LVP signal cannot be generated while the hold signal is present. In addition, the hold signal passes through OR gate 221 to the set zero input of flip-flop 220 so that, should the hold signal be generated during the last vehicle passage interval, the LVP signal will be removed, and the traffic phase will no longer be in its last vehicle passage interval. Once the hold signal terminates, the gap timing circuitry again commences to operate.

This hold is only applied to the odd interval sequence unit, and so the even interval sequence unit steps from its vehicle interval in counter position 5 to the counter position 6 preparatory interval. Within the even phase selection circuitry, the signals B2PFF1, A2PMFF1, and ISE(6) are applied to an AND gate (analogous to gate 502 of FIG. 9). As a consequence, that AND gate generates a signal which causes generation of the signal A2PNFFS1 to set to its one condition the phase next flip-flop 118 within phase control unit A2. The A2PNFF1 signal passes through gate 406 to AND gate 404, resulting in the ISE-PL signal which causes another advance 75

pulse to step the even interval sequence unit to its yellow clearance interval of counter position 7.

After the clearance interval and the all-red interval have been timed, the even counter reaches its position 9, the transfer position. It then sends a signal through gating within the even phase selection circuitry (analogous to the gating of FIG. 10) to cause the ISE-TR signal which transfers right-of-way to phase A2, returning the counter within the even interval sequence unit to its one position.

Within the odd hold gating circuitry of FIG. 11, inverter 602 receives no input and so it applies an output through gate 590 to gate 592. The A2 phase memory flip-flop 116 (FIG. 4) remains in its one condition until counter position 5, therefore the A2PMFF1 signal is also applied to gate 592. Since the calls for right-of-way on phases A3 and A4 are still present, the 3+4 call signal is still applied to gate 592, and gate 592 maintains the A1 hold signal. Therefore, phase control unit A1 and the odd interval sequence unit remain in their counter position 5. Once the even interval sequence unit has reached its position 5 for traffic phase A2, an input is supplied to inverter 602, and so the inverter removes the signal applied through OR gate 590 to AND gate 592. Additionally, the PMFF 116 within phase control unit A2 is returned to its zero condition, removing the A2PMFF1 signal from gate 592. Consequently, the A1 hold signal terminates, and timing is continued in the odd interval sequence unit.

The gap timing circuitry (FIG. 6) then commences to measure the gaps between vehicles on traffic phase A1. In the event a new platoon of traffic is now approaching the intersection on phase A1, that platoon of traffic will operate the gap timing circuitry and the vehicle timing circuitry of FIG. 4, as described above. The maximum timing circuitry of FIG. 4 commenced operation as soon as the conflicting right-of-way call was received. However, since gate 181 is blocked, the maximum timer output from Schmitt trigger 178 is not able to step the odd interval sequence unit to its preparatory position before the even interval sequence unit has reached its counter position 5 for traffic phase A2, thereby terminating the hold signal. After the hold signal ends, the vehicle interval of phase A1 is terminated by either the gap timing circuitry or the maximum timing circuitry. The odd interval sequence unit then steps to its counter position 6, the preparatory position. The even interval sequence unit operates in its usual manner for traffic phase A2, and when the vehicle interval for phase A2 terminates, either due to a gap in the traffic or due to the maximum timer, the even interval sequence unit also steps to its preparatory position. The phase sequence unit common circuitry of FIG. 8 then generates the preparatory leave signal to cause a vehicle clearance interval followed by the all-red interval and the transfer interval. Right-of-way is then transferred to traffic phases A3 and A4.

TRANSFER FROM DOUBLE-ENDED OPERATION TO SINGLE-ENDED OPERATION

With the right-of-way now on phases A3 and A4, assume that next a call for right-of-way is received from only traffic phase A2, and that no call for right-of-way is received from any odd traffic phase. The A2 call terminates the Σ no call signal within the even interval sequence unit and initiates the ISO call away signal from the odd phase selection circuitry (see FIG. 9). As a consequence, the counters within the two interval sequence units step from their vehicle interval in counter position 5 to the preparatory interval of counter position 6.

The A2PMFF1 signal passes through OR gate 432 within the phase sequence unit common circuitry of FIG. 8 becoming the 1+2 call signal which is applied to the first input of AND gate 436 and to the first input of AND gate 444. Gates 436 and 444 receive as inputs the signals A3PFF1 and A4PFF1 respectively. When the odd interval sequence unit has reached its preparatory position,

gate 436 receives the signal ISO (6) and transmits a signal through OR gate 438 to the first input of AND gate 440. When the even interval sequence unit has reached its preparatory interval, gate 444 receives the ISE (6) signal and transmits a signal through gate 446 to the second input of gate 440. On coincidence of these two inputs to gate 440, that gate sends a signal through OR gate 450 to OR gate 426 where it becomes the lock detector signal that is applied to the DMV 108 within each phase control unit. The output of gate 450 also passes through timer 452 to Schmitt trigger 454 to initiate the street II to street I change signal that is applied as an input to AND gate 470. Since there has not been a call for right-of-way on either phase A1 or phase B1, gate 470 receives as inputs the signals A1PMFF0 and B1PMFF0. In addition, the output of gate 438 is applied to gate 470. Therefore gate 470 generates a signal which passes through OR gate 466 to the set one input of ISONCFF 400. The one output of ISONCFF 400 indicates there has not been a call for right-of-way on an odd traffic phase, and so the system is to operate in even phase single-ended operation. This ISONCFF1 signal passes through OR gate 405 to one input of AND gate 402 which receives the ISO(6) signal at its other input. As a consequence, gate 402 generates the odd interval sequence unit preparatory leave signal which is applied to OR gate 140 within the odd interval sequence unit gating and timing circuitry, as depicted in FIG. 5. This results in the generation of the advance pulse which steps the interval sequence unit counter to its position 7, the vehicle clearance position.

Simultaneously, the street II to street I change signal is applied to the gating circuitry within the even phase selection circuitry to cause the generation of the A2PNFFS1 signal which sets to the one position the phase next flip-flop 118 within phase control unit A2. The A2PNFF1 signal then passes through OR gate 406 within the phase sequence unit common circuitry of FIG. 8 to one input of AND gate 404. Since gate 404 receives the ISE(6) signal at its other input, it generates the ISE-PL signal which causes the even interval sequence unit to leave its preparatory interval and step to counter position 7, the vehicle clearance interval. The two interval sequence units then time the appropriate vehicle clearance intervals and all-red intervals and step to their counter positions 9, the transfer position.

The even interval sequence unit applies the ISE(9) signal to the phase flip-flop 120 within phase control unit A4, returning that flip-flop to its zero condition. As a consequence, the even transfer gating (analogous to FIG. 10) generates the ISE-TR signal which is applied through OR gate 140 within the even interval sequence unit to cause a transfer pulse which steps the counter of the even interval sequence unit to its counter position one and which transfers right-of-way to traffic phase A2. However, within the transfer gating circuitry for the odd traffic phases no inputs are applied to OR gates 536 and 540 (FIG. 10). As a consequence, gate 544 does not apply an input to AND gate 546, and so gate 546 is blocked. Therefore, the ISO-TR signal is not generated, and the odd interval sequence unit rests in its counter position 9. Thus, single-ended operation has been achieved.

TRANSFER FROM SINGLE-ENDED OPERATION TO DOUBLE-ENDED OPERATION ON THE SAME STREET

If a call for right-of-way is received on a non-conflicting traffic phase during single-ended operation, for example a call on traffic phase B1 during single-ended operation on phase A2, the B1PMFF1 signal passes through OR gate 550 (FIG. 9) to one input of AND gate 548. During positions 1-5 of the counter within the even interval sequence unit, a signal passes from gate 562 through gate 558 to one signal input of gate 560. Since the system is operating in even phase single-ended operation, the ISONCFF1 signal is applied to gate 560. Therefore, the

gate passes a signal to the second input of gate 548, except when an advance pulse blocks gate 560.

The output of gate 548 is applied to AND gate 572 which also receives as inputs the B1PMFF1 signal and the A2PFF1 signal that passes through OR gate 552. As a consequence, gate 572 generates an output which is applied through OR gate 578 to OR gate 426 within the common circuitry of FIG. 8. At gate 426, this signal becomes the lock detector signal which applied to DMV 108 within each phase sequence unit. The output of gate 572 also passes through OR gate 516 to fire Schmitt trigger 518 generating the BIPNFFS1 signal which sets to its one condition the phase next flip-flop 118 within phase control unit B1.

The BIPNFF1 signal is then applied to OR gate 536 (FIG. 10) from which it passes through gates 538 and 544 to AND gate 546. Since gate 546 is also receiving the ISO9 signal, it generates the ISO-TR signal, and the odd interval sequence unit counter steps to its one position to provide right-of-way for traffic phase B1.

TRANSFER FROM SINGLE-ENDED OPERATION TO DOUBLE-ENDED OPERATION ON THE OTHER STREET

If a call for right-of-way is received from the other street while the system is controlling the intersection in single-ended operation, the circuitry of FIG. 9 causes the proper transfer. Assume that while the system is in single-ended operation on phase A2, calls for right-of-way are received from phases A3 and A4. The A2PFF1 signal passes through OR gate 552 to one input of AND gate 580. The A3PMFF1 signal passes through OR gate 582 to the other input of gate 580. Therefore, gate 580 generates a signal that passes through OR gate 584 to become the ISE call away signal. This results in the counter within the even interval sequence unit stepping from its counter position 5, the vehicle interval, to its counter position 6, the preparatory interval.

AND gate 476 (FIG. 8) then receives signals at all of its inputs. Since there has not been a call to transfer right-of-way from a B traffic phase to a corresponding A traffic phase, the B/A call signal is not present, and so inverter 484 applies a signal to AND gate 476. During even phase single-ended operation, the odd interval sequence counter is resting in its transfer position, and so the ISO (9) signal passes through OR gate 474 to AND gate 476. When the even interval sequence counter is in its preparatory position, the ISE (6) signal passes through OR gate 478 to AND gate 476. During even phase single-ended operation, the ISONCFF1 signal passes through OR gate 480 to AND gate 476. Consequently, gate 476 applies a signal to AND gate 486. Since the system is only providing right-of-way to traffic phase A2, the signals A3PFF0, B3PFF0, A4PFF0, and B4PFF0 are applied to the inputs of gate 486. The signals A3PMFF1 and A4PMFF1 pass through OR gate 408 to become the 3+4 call signal which is applied to gate 486. Consequently, gate 486 transmits a signal through OR gate 424 to OR gate 426 where it becomes the lock detector signal applied to DMV 108 within each phase control unit. The output of gate 424 also passes through time delay 428 which introduces a short delay before turning on Schmitt trigger 430 to generate the street I to street II change signal.

The street I to street II change signal is applied within the odd phase selection circuitry of FIG. 9 to one input of AND gate 532. Gate 532 also receives as inputs the A3PMFF1 signal and the B3PMFF0 signal, and so gate 532 passes a signal through gate 510 to turn on Schmitt trigger 512, thereby generating the A3PNFFS1 signal which is applied to the set-to-one input of the phase next flip-flop 118 within phase control unit A3. Corresponding gating within the even phase selection circuitry results in the generation of the A4PNFFS1 signal which likewise sets to the one condition the PNFF 118 within phase control unit A4.

The A4PNFF1 signal passes through OR gate 406 within the phase sequence unit common circuitry of FIG. 8 to the first input of AND gate 404, which receives the ISE (6) signal at its second input. Consequently gate 404 generates the ISE-PL signal to cause the even interval sequence unit to leave its preparatory position 6 and to enter the vehicle clearance interval. After the vehicle clearance interval and the all-red interval have been timed, the even interval sequence unit reaches its counter position 9, the transfer position. In counter position 9, the PFF 120 (FIG. 4) within phase control unit A2 is returned to its zero condition to give an A2PFF0 signal, and, with the B2PFF0 signal also present at gate 542 in FIG. 10 the A3PNFF1 signal passes through OR gate 540, AND gate 542, and OR gate 544 to one input of AND gate 546. Since the odd interval sequence unit is resting in its counter position 9, gate 546 generates the ISO-TR signal which is applied through OR gate 140 within the odd interval sequence unit gating and timing circuitry (FIG. 5) to cause an advance pulse which returns the counter to its position one and transfers right-of-way to traffic phase A3. Gate 472 (FIG. 8) then returns ISONCFF 400 to its zero condition. In like manner, the ISE-TR signal is generated, causing an advance pulse within the even interval sequence unit which steps that counter to its position one and transfers right-of-way to traffic phase A4.

TRANSFER FROM SINGLE-ENDED OPERATION TO SINGLE-ENDED OPERATION ON THE SAME STREET

If the system is controlling the intersection in single-ended operation when a call is received for single-ended operation from a conflicting traffic phase on the same street, then the system transfers to single-ended operation for that traffic phase. For example, assume that the system is operating in odd phase single-ended operation on traffic phase A1, when a call for right-of-way is received from traffic phase B1. The call for right-of-way on phase B1 terminates the Σ no call signal within the odd interval sequence unit, and therefore causes the odd counter to step from its position 5 to position 6, the preparatory position. The signals A1PFF1 and ISO (6) are then applied as inputs to AND gate 514 (FIG. 9) within the even phase selection circuitry. Since there has not been a call for right-of-way on street II this gate also receives the $\overline{3+4}$ call signal. As a consequence, the gate generates an output which causes the B1PNFFS1 signal that is applied to the phase next flip-flop 118 within phase control unit B1 to set PNFF 118 to its one condition. Then, within the odd transfer gating circuitry (FIG. 10) the B1PNFF1 signal passes through OR gate 536 to the first input of AND gate 538. AND gate 538 also receives the A4PFF0 signal and the B4PFF0 signal, and so it generates an output which is applied through OR gate 544 to AND gate 546. When the odd interval sequence unit reaches its counter position 9, gate 546 receives the ISO (9) signal and generates the ISO-TR signal which returns the odd interval sequence unit to its counter position 1 and transfers right-of-way to traffic phase B1. Thus, the system remains in single-ended operation, but with right-of-way on phase B1.

Assume that the system is in single-ended operation on traffic phase A2 when a call for single-ended operation on phase B2 is received. The system commences its transfer from single-ended operation to single-ended operation on the same street, as in the preceding example. If a call for right-of-way from a non-conflicting traffic phase, for example phase A1, is received during the time that the clearance interval is being provided for phase A2, that call can be answered immediately. The A2PFF1 signal passes through gate 552 (FIG. 9) to one input of AND gate 554. The B2PNFF1 signal passes through OR gate 556 to the other input of gate 554. Consequently, gate 554 transmits a signal through OR gate 558 to one signal input of gate 560. Since the system is presently operating in even

phase single-ended operation, the ISONCFF1 signal is also applied to gate 560. Except during the presence of the advance pulse, gate 560 then transmits a signal to one input of AND gate 548. The A1PMFF1 signal passes through OR gate 550 to the other input of gate 548. The output of gate 548 then is applied to one input of AND gate 570. Since there has not been a call for right-of-way from phase B1 but there has been a call from phase A1, gate 570 also receives as inputs the signals B1PMFF0 and A1PMFF1. The output of gate 552 is also applied to gate 570. Consequently, gate 570 generates an output which passes through gate 578 to become the odd lock detector signal which is transmitted via OR gate 426 (FIG. 8) to DMV 108 within each phase control unit. The output of gate 570 also passes through OR gate 504 to fire Schmitt trigger 506 generating the A1PNFFS1 signal which sets to its one condition the phase next flip-flop 118 within the phase control unit A1.

The A1PNFF1 signal then passes through OR gate 536 (FIG. 10) to one input of AND gate 538. Gate 538 also receives the signals A4PFF0 and B4PFF0, and so gate 538 transmits a signal through OR gate 544 to one input of AND gate 546. Since the odd interval sequence unit is resting in its counter position 9, gate 546 receives the ISO9 signal and generates the ISO-TR signal which causes an advance pulse within the odd interval sequence unit to return the odd counter to its position one and to provide right-of-way for traffic phase A1. Thus, if a call for right-of-way is received from a non-conflicting phase during the clearance interval of a transfer from single-ended operation to single-ended operation on the same street, that calling phase is immediately given right-of-way without having to wait for the clearance interval to end. As a consequence, the vehicle which has caused the call on phase A1 does not have to wait the several seconds of the clearance interval. This means that that vehicle may not have to come to a stop before receiving right-of-way.

The above examples are illustrative of the operation of the system in transferring right-of-way from one phase to another and in stepping through the various intervals of each right-of-way period. The numerous other possible sequences of right-of-way transfer can be traced through the figures in a manner similar to that above.

The traffic control system of the present invention is capable of operation as a semi-actuated controller which returns right-of-way to one traffic phase and rests on that traffic phase in the pedestrian interval of counter position 2 until it is called to a conflicting traffic phase. To provide this semi-actuated operation, switches 320 and 322, within the phase control unit of FIG. 4, are closed. These switches, which may be ganged to operate together, are referred to as the semi-actuated call or semi-call switches. When operating in this manner, the vehicle interval of counter position 5 is omitted, and the minimum time which the controller remains in the pedestrian interval of counter position 2 is determined by the adjustment of the maximum timer circuitry comprising variable resistor 172 and capacitor 170, rather than by the usual pedestrian timer of resistor 121 and capacitor 127. Within the phase control unit, the PFF1 signal passes through semi-call switch 320 in its closed position to OR gate 244, the output of which is connected to the set zero input of PMFF 116. The second side of semi-call switch 320 also connects through diode 324 to provide the semi-call signal to the gating and timing circuitry of FIG. 5. The semi-call signal is applied to one input of AND gate 328, the other input of which receives the counter position 5 signal from gate 64 (FIG. 3). The output of gate 328 is applied as an input to OR gate 140. Thus when the semi-call switch is closed, the output of gate 328 passes through OR gate 140 to cause an advance pulse during counter position 5. Therefore, position 5 is "skipped," in effect.

The semi-call signal is also applied to one input of AND gate 330 (FIG. 5) which receives the counter position 2 signal from gate 58 (FIG. 3) at its second input.

The output of gate 330 passes through OR gate 156 to the inhibit input of gate 141, and to the interval timer reset circuitry. Thus, when semi-actuated operation is called for, gate 141 is blocked during counter position 2, and the pedestrian timer, comprising resistor 121 and capacitor 127 (FIG. 4) is clamped to ground. Consequently, the pedestrian timer cannot cause an advance pulse at the end of the normal pedestrian interval. Once right-of-way is transferred to this traffic phase, the maximum timer comprising resistor 172 and capacitor 170 commences to build up voltage. This voltage is passed to Schmitt trigger 178 within the gating and timing circuitry of FIG. 5, and so the interval sequence unit is held in its counter position 2 until the maximum timer output turns on Schmitt trigger 178 to trigger DC DMV 180.

The output of DC DMV 180 is blocked from passage through gate 181 by the semi-call signal which passes through OR gate 259 to the inhibit input of gate 181. The output of DMV 180 is also applied as an input to AND gate 332 which receives the semi-call signal at its second input. Thus, the output of DMV 180 passes through gate 332 and through gates 148, 150, and 152 to trigger one-shot 154, causing an advance pulse which steps the counter to position 3, the pedestrian clearance position. AND gate 334 (FIG. 5) receives as inputs the semi-call signal, the counter position 2 signal, and the advance pulse. Therefore, the advance pulse which terminates the pedestrian interval of counter position 2 passes through gate 334 to OR gate 164 where it becomes the maximum timer reset signal that is applied through OR gate 174 within the phase control unit of FIG. 4 to turn on gating amplifier 176. As a consequence, the maximum timer is reset at the end of the pedestrian interval.

The counter position 2 signal and the semi-call signal are applied as inputs to AND gate 336 within the gating and timing circuitry of FIG. 5. The output of gate 336 passes through OR gate 252 to one input of AND gate 254. When there has not been a call for right-of-way from a conflicting traffic phase, a signal passes from gate 256 through OR gate 258 to the second input of gate 254. As a consequence, gate 254 applies an input which inhibits gate 150. Thus, the output of OR gate 148 cannot pass through gate 150, and so no advance pulse can be generated until there has been a call for right-of-way from a conflicting traffic phase.

The semi-call signal is also applied to the inhibit input of gate 250 within gating and timing circuitry of FIG. 5 so that when semi-actuated operation is called for, the counter position 5 signal cannot pass through gates 250 and 252 to gate 254. In addition, the semi-actuated call signal passes through OR gate 177 (FIG. 5) to block gate 162 to prevent the generation of the maximum timer reset signal. Within the counter circuitry of FIG. 3 the semi-call signal passes through OR gate 78 to block gate 79 and to provide an enabling input to gate 86.

The traffic control system of the present invention is also adapted to receive the signal "stop timing." Within each phase control unit this signal is applied through OR gate 128 in FIG. 4 to reset the interval timer, the maximum timer, the vehicle timer, and the gap reduction timer. In addition, the stop timing signal is applied through OR gate 206 to the inverting amplifier gate 208 of FIG. 6 to clamp and thus keep reset the gap reduction timer of FIG. 6. The stop timing signal might be utilized, by way of examples, to permit manual operation of the control system, to permit insertion of a sub-cycle at some point within the regular cycle of the control system, or to permit use of a pre-emptor to provide emergency vehicle right-of-way.

Obviously other features can be added to the traffic system of the present invention. By way of example, a variable initial interval timing circuit could be added to the system. Such a circuit is disclosed and claimed in co-pending patent application Ser. No. 607,811, filed Jan. 6, 1967, by Peter C. Brockett, now U.S. Patent No. 75

3,464,059, assigned to the same assignee as the present invention. Additionally, the traffic control system can have assorted safety circuitry added to it to insure that right-of-way is not simultaneously applied on conflicting traffic phases. Such safety circuitry might, for example, consist of gating circuits to which right-of-way indications are provided so that the gates generate an output if conflicting right-of-way intervals are present simultaneously. This output then causes a red indication for each traffic phase. Such circuits are well-known in the art.

Certain features of the system can be omitted for particular traffic phases, if desired. For example, it might be preferred not to use the gap timing circuitry of FIG. 6 with the left-turn traffic phases. Within the phase control units associated with the left-turn phases, variable resistor 182 (FIG. 5) is set for the critical gap length between consecutive vehicles, and no connections are made to the inhibit inputs of gates 186 and 246 and to the outputs of gate 209 and diode 216. In like manner, this circuitry could be left unused on a straight-through traffic phase if desired. The all-red interval of counter position 8 could be skipped on a particular traffic phase by generating a command to skip all-red during the one output of phase flip-flop 120 (FIG. 4) for that traffic phase and by passing this skip all-red command and the counter position 8 signal through an AND gate to OR gate 140 within the circuitry of FIG. 5.

In the above illustrative example, the system has been depicted controlling four traffic phases including pedestrian features and four traffic phases not having pedestrian features. This, of course, is only one example of the type of intersection which might be controlled by this system. If an intersection requires a different number of pedestrian phases, then the pedestrian circuitry is provided in the necessary number of phase control units. Additionally, if a particular intersection requires fewer than eight phases, the unneeded phase control units (FIG. 4) are omitted. Since all of the circuitry uniquely associated with a particular traffic phase is within one phase control unit and is operated under command of a common interval sequence unit and the common phase sequence unit, variation in the number of traffic phases at an intersection only requires a variation in the number of phase control units provided. If fewer phase control units are utilized than are depicted in the above illustrative example, the phase sequence unit and the interval sequence unit continue to operate as described above. The one or more phase control units which in fact are omitted appear to the phase sequence unit and to the interval sequence unit to be present but to lack any right-of-way calls. Therefore, the system never attempts to assign right-of-way to that missing traffic phase. Should the intersection requirements later increase, additional phase control units can then be added. The modular design of the system permits great flexibility in its use.

Although preferred embodiments of particular components of the traffic control system have been described, these are illustrative examples only, and they are not limitations. Other equivalent devices can be used in place of one or more of these components and still be within the scope of the present invention.

The invention has been discussed with reference to a particular street intersection design. This, of course, is only illustrative, and the invention can be utilized in controlling numerous other combinations of street intersections.

Particular logic combinations are disclosed in the above embodiment, but obviously voltage polarity changes, inverting amplifiers, isolating amplifiers, current amplifiers, isolating diodes, delay multi-vibrators, and other minor components can be added as required. While positive logic has been shown, with appropriate modification negative logic can be utilized within the circuitry. By proper optimization of the design, certain of the components might be eliminated, but they have been shown in the above

preferred embodiment in the interest of clarity. To accommodate the current required by the traffic control signal lamp loads, the output lines 262, 266, 270, 300, 304, and 318 can control external relays or switching diodes, such as signal control rectifiers, for example, to switch current to the signal lamps.

The start signal referred to above may be provided by manual control or automatically. One form of automatic start signal is illustrated in U.S. Patent 3,267,424 issued Aug. 16, 1966, for example.

Thus among others, the several objects of the invention, as specifically aforementioned, are achieved. Although alternative forms of the invention have been pointed out above, obviously numerous other changes in construction and rearrangement might be resorted to without departing from the spirit of the invention.

I claim:

1. A traffic-actuated multi-phase intersection control system for providing control periods to selected ones of the traffic phases at an intersection, each control period having a plurality of intervals including a right-of-way interval during which traffic on said selected traffic phases is permitted to proceed through the intersection, said control system comprising in combination:

a first group of phase control means, each individual 25 associated with one of a first group of mutually conflicting traffic phases at said intersection;

a second group of phase control means, each individually associated with one of a second group of mutually conflicting traffic phases at said intersection; 30 each phase control means including:

(1) first circuit means for coupling vehicle detection means thereto, said first circuit means developing traffic demand indications in response to vehicles at said vehicle detection 35 means;

(2) signal control circuits for providing control period interval indications for its associated traffic phase;

(3) a memory means capable of assuming a first 40 condition and a second condition, said memory means assuming said first condition upon receipt of a vehicle detection indication by its phase control means;

a first interval sequencing means coupled to each phase 45 control means of said first group of phase control means;

a second interval sequencing means coupled to each phase control means of said second group of phase control means;

phase sequencing means coupled to each said phase control means and to each said interval sequencing means, said phase sequencing means including phase selection means responsive to said memory means conditions for providing control assignment signals 55 to a first selected phase control means for said first group of phase control means and to a second selected phase control means from said second group of phase control means, to enable said first and second selected phase control means to provide control period interval indications including right-of-way interval indications, said second phase control means associated with a traffic phase non-conflicting with the traffic phase associated with said first selected phase control means;

each phase phase control means further including second circuit means responsive to said control assignment signals and to said traffic demand indications for developing an electrical signal representing the duration of selected intervals of said control periods; each said interval sequence means including:

(1) electronic interval stepping means having a plurality of stepping positions, each position corresponding to an interval of a control period,

5

75

said stepping means providing an output signal individual to each position;

(2) pulse generating means responsive to each said electrical signal and coupled to said stepping means and to said second circuit means for applying a pulse to said stepping means when said electrical signal indicates the interval duration has reached a pre-set value, said stepping means stepping from one of its positions to another of its positions upon receipt of said pulse, thereby terminating one interval of said control period and initiating another interval of said control period, said pulse generating means also applying said pulse to said second circuit means to cause said electrical signal to indicate termination of said one interval;

said signal control circuits developing said right-of-way interval indications in response to said control assignment signals and to said stepping means output signals;

said phase sequencing means further including control gating means responsive to said stepping means output signals, to said memory means conditions, and to said control assignment signals for synchronizing operation of said first and second interval sequencing means stepping means at selected ones of said plurality of positions.

2. The system of claim 1 in which said phase sequencing means further includes hold circuit means responsive to said control assignment signals and to said memory means condition for applying a holding signal to one interval sequencing means to hold the stepping means in a position corresponding to an intermediate interval of its control period while the other interval sequencing means steps through its stepping positions and transfers right-of-way to reach the corresponding intermediate interval position for a traffic phase which is non-conflicting with the traffic phase for which said one interval sequencing means is holding the stepping means.

3. The system of claim 2 in which said hold circuit means includes solid state gating means individual to each phase control means, the solid state gating means individual to any phase control means having:

a first input coupled to the memory means within the phase control means associated with a first non-conflicting traffic phase;

a second input coupled to the phase control means associated with a second non-conflicting traffic phase; a third input coupled to the memory means within the phase control means associated with conflicting traffic phases;

said gating means producing a holding signal on coincidence of said first non-conflicting phase control means memory means assuming its first condition and a conflicting phase control means memory means assuming its first condition while said second non-conflicting phase control means providing control period interval indications.

4. The system of claim 1 in which said phase selection means includes a plurality of solid state gating means for providing control assignment signals in response to selected combinations of said memory means conditions and said control period interval indications and said stepping means output signals.

5. The system of claim 1 in which each said interval sequencing means further includes gap measuring means responsive to the time spacing between consecutive vehicle actuation inputs on its associated traffic phase having right-of-way to cause said interval sequencing means to step through positions to transfer right-of-way to another associated traffic phase when said gap measuring means indicates that the time spacing between consecutive vehicle actuation inputs on said associated traffic phase is in excess of a permissible time spacing gap duration during the time the memory means in a phase

control unit associated with a conflicting traffic phase is in its first condition.

6. The system of claim 5 in which said gap measuring means further includes means to progressively reduce the permissible time spacing gap duration when the memory means in a phase control unit associated with a conflicting traffic phase is in its first condition. 5

7. The system of claim 1 in which said signal control circuits include means for developing control period interval indications for vehicular traffic control indications and means for developing control period interval indications for pedestrian traffic control indications. 10

8. The system of claim 1 in which at least one phase control means includes manually-operable switching means capable of being set to a first position and to a second position, and in which said memory means is caused to assume its first condition when said switching means is in its first position and the traffic phase associated with its phase control means does not have right-of-way. 15

9. The system of claim 1 further including: 20
traffic signalling means coupled to said signal control circuits for providing control indications in response to control period interval indications;
and vehicle detection means coupled to said first circuit means for applying vehicle detection indications thereto in response to vehicles at said detection means. 25

10. The system of claim 1 in which said control gating means includes:

means for synchronizing stepping operation of said 30
stepping means at a selected one of said plurality of positions in response to combinations of said stepping means output signals and said memory means conditions and said control assignment signals indicating that both said first and said second selected phase control means are to terminate right-of-way interval indications;
and, means for permitting independent stepping operation of one of said stepping means in response to 40

other combinations of said stepping means output signals and said memory means conditions and said control assignment signals indicating that one of said selected phase control means is to terminate right-of-way interval indications, while permitting the other of said stepping means to remain in a selected one of said plurality of positions.

11. The system of claim 1 in which said control gating means includes:

first solid state control gate means for providing a first further electrical signal to said first interval sequencing means upon coincidence of a first one of said control assignment signals and a selected first interval sequencing means stepping position output signal, said synchronizing gating means coupled to said first interval sequencing means pulse generating means to cause a pulse therefrom on occurrence of said first further electrical signal;
second solid state control gate means for providing a second further electrical signal to said second interval sequencing means upon coincidence of a second one of said control assignment signals and a selected second interval sequencing means stepping position output signal, said synchronizing gating means coupled to said second interval sequencing means pulse generating means to cause a pulse therefrom on occurrence of said second further electrical signal.
